UNITED STATES PATENT OFFICE.

WINTHROP K. HOWE AND CHARLES S. BUSHNELL, OF ROCHESTER, NEW YORK, AS
SIGNORS TO GENERAL RAILWAY SIGNAL COMPANY, OF ROCHESTER, NEW YORK.

TRAIN CONTROL.

Application filed July 26, 1923. Serial No. 653,898.

This invention relates to train control systems designed to give full protection under the varying operation conditions encountered in practice.

5 In accordance with this invention, it is proposed to communicate or transmit the desired controlling influences from the trackway to the moving trains by a means of the inductive non-physical contact type which is continuously effective and affords what is conveniently termed continuous inductive control; impose upon the train at all times predetermined speed restrictions which are automatically varied in accordance with traffic conditions and the location of the train so as to be adequate for safety and at the same time suitable for providing a high degree of facility of train movement, due allowance being made for the variable lengths of blocks commonly encountered in practice; to require the engineer to acknowledge by a positive act each unfavorable signal indication, either caution or stop, which is given by the trackway fixed signals, or be suitably penalized for his neglect; to permit the engineer under automatically imposed restrictions to manually cut out or render ineffective the automatic control of the train while traveling in unequipped or non-signalled territory, a distinctive indication in the cab signifying that the train is traveling without protection being continuously displayed while the train is in such unsignalled territory, and the automatic control being automatically restored as soon as the train again comes into equipped or signalled territory; to give at times cab signal indications which correctly show the existing traffic conditions ahead, whether clear, or caution, these cab signal indications being automatically changed instantly as the traffic conditions become more favorable; to give the engineer a reliable warning signal prior to every automatic brake application, if desired, so as to facilitate handling of the train by the engineer safely and with the least delay; to provide a suitable penalty for failure on the part of the engineer to govern his train properly in accordance with the information provided; to make provision for manual adjustment of the apparatus on the locomotive or other vehicle so that it may be used in either freight or passenger service as desired; and in general make adequate provision for the various features of

automatic, manual, and combined automatic and manual control needed to satisfy the varying and peculiar requirements of an automatic train speed control system adaptable to practical railroad operating conditions.

Other objects, purposes, and characteristic features of the invention will appear as the description thereof progresses.

In describing the invention in detail, reference will be made to the accompanying drawings, in which:

Figure 1 shows a side elevation of a pony truck of a typical locomotive, together with the outer casing containing the car-carried apparatus of the present invention bolted thereto, part of which is broken away to illustrate how the mechanism casing is spring supported therein;

Fig. 2 is a front elevation of the apparatus shown in Fig. 1, portions thereof being omitted for clearness;

Fig. 3 is a plan view of one compartment and a portion of the other compartment of the mechanism casing with the cover removed, and shows a portion of the train control apparatus contained therein;

Fig. 4 is a sectional view taken on the line 4—4, Fig. 3, as viewed in the direction of the arrows, and shows the speed responsive device and cam operating gearing;

Fig. 5 is a similar view taken on the line 5—5, Fig. 3;

Fig. 6 is an enlarged sectional elevation taken on the line 6—6, Fig. 5;

Fig. 7 is an enlarged sectional view taken on the line 7—7, Fig. 3, as viewed in the direction of the arrows;

Fig. 8 is a section taken on the line 8—8, Fig. 3, as viewed in the direction of the arrows, and shows the normally closed speed-distance or cam-governor contacts;

Fig. 9 is a section taken on the line 9—9, Fig. 3, and shows normally open speed-distance contacts;

Fig. 10 shows the distance contacts;

Fig. 11 shows the speed contacts operated by the speed responsive device;

Fig. 12 illustrates a preferred form of car-carried relay, which is provided with contacts similar to the contacts shown in Figs. 8 to 11;

Fig. 13 is a plan view of the relay shown in Fig. 12;

Fig. 14 shows diagrammatically a section

of trackway with the necessary trackway apparatus and wiring for a train control system embodying the present invention, and also illustrates conventionally the receiving 5 and amplifying apparatus of the car-carried apparatus including a three-position main control relay;

Fig. 15 is a simplified wiring diagram of the car-carried apparatus showing the various relays, cam operated contacts and brake control device in a conventional manner;

Fig. 16 illustrates a more complete form of the E. P. V. and WS group of the wiring diagram shown in Fig. 15, which is employed for a locomotive used in both passenger and freight service; and

Fig. 17 shows a modified type of car-carried apparatus similar to that illustrated in Fig. 15, in which no acknowledgment of a 20 caution or a danger signal is required.

Generally speaking, in practicing the present invention, alternating current is transmitted down one of the track rails through the usual track relay (or the axles of a train, 25 if the block happens to be occupied) back through the other rail, this current corresponding to the usual track circuit current and conveniently referred to as loop circuit current; and another alternating current, 30 preferably of the same frequency but displaced in phase as much as possible from the first mentioned current is transmitted through said two track rails in multiple and back over a return wire, this other current being called the simplex circuit current. 35 These currents in the track rails are detected or picked up on the car by magnetic induction, amplified, and then used to control a suitable two-element or polyphase alternating current relay. These currents in the 40 track rails are controlled by the usual track circuits so that their existence and phase relation in any given block depends upon the proximity of a train ahead. The loop circuit current and the simplex circuit current in the track rails are separately detected or 45 picked up by suitable receiving devices on the vehicle, amplified, and then used to control a two-element or polyphase alternating current relay or equivalent electro-responsive device. This relay governs the cab signal indications, the speed governed brake 50 control apparatus, and the other devices on the car used in attaining the results contemplated by this invention.

In describing the invention in detail, the apparatus will first be described, after which the operation of the system and the manner in which the different parts cooperate will 55 be explained.

Structure of car-carried apparatus (mounting and transmitting connection).

In Figs. 1 and 2 has been shown in dot 60 and dash lines a skeleton outline of a por-

tion of a pony truck of a locomotive, showing the main frame 1, a cross beam 2 mounted thereon in any suitable manner, and a journal box 3 in which is journaled the axle 4 for the car wheel 5. The track rail is designated 6. The outline of the locomotive cylinder 9 is shown to illustrate that sufficient clearance is provided for the apparatus presently to be described.

Mechanism casings.—To the cross beam 2 is fastened a bracket 7, which in cooperation with another bracket 8 attached to the main frame 1, supports the outer casing or housing 10 for the car-carried apparatus, this outer casing being bolted to these brackets by bolts 11. This outer casing 10 is provided with a hinged cover 12, having a gasket in a groove in the edge thereof to fit tightly on the upper edges of the casing; and this cover is held closed by suitable spring hasp 85 fasteners 14 (only one being shown), which may be locked or sealed in the usual way.

It is essential to protect the relays and other sensitive devices in the mechanism casing 18 against the shock, jar and vibration 90 to which it is necessarily subjected when carried on a locomotive or other railway vehicle. This protection may be afforded in various ways and the particular expedient adapted is not material to the present invention. In the specific construction illustrated, which is not claimed in this application, the inner mechanism casing 18 is yieldingly supported within the outer casing 10 upon cushioning springs. As shown in Fig. 1, the inner casing 18 is supported at each corner by two opposing compression springs 16 and 17, preferably under some initial tension depending upon the weight of the inner casing. The upper spring 16 is supported 100 between two projecting lugs 20 and 21, the lower lug 21 being integral with the inner mechanism casing 18 and the upper lug 20 integral with the outer casing 10. The lower spring 17 is interposed between the middle lug 21 and a pad or boss 22 on the bottom of the outer casing 10. The ends of these springs fit over bosses on their respective supporting lugs. The boss in the upper lug 20 is preferably made adjustable by a 110 bolt and lock nut as shown.

In addition to the spring support just described, it is considered desirable to provide frictional resistance opposing the movement 120 of the inner casing 18 with respect to the outer casing 10 so as to reduce the amplitude of vibration, absorb the energy tending to produce continued oscillation, and in general stabilize the inner casing. As shown, a flat spring 23 is fastened at its lower end to the outer casing 10, and the upper end of this spring is faced on both sides with pads 24 of suitable friction material, such as commonly used for automobile brake linings. A strap or loop 25 is fastened to the inner cas- 130

ing 18 by suitable bolts (not shown), and is drawn down to establish pressure between the pads 24 and the inner casing and said strap respectively, this strap being preferably resilient or spring supported to yieldingly maintain the desired pressure between the friction surfaces. One of these springs 23 and associated parts is preferably located at each side and end of the inner casing 18.

10 It will be evident that these springs 23 and their associated friction pads provide frictional opposition to vertical and lateral movement of the inner casing 18 with respect to the outer casing 10.

15 *Transmission.*—The system of this invention involves a driving connection to the car wheels; and while this driving connection may be provided in various ways, in the particular arrangement shown, a spiral gear 27 is bolted to the outer end of the pony truck axle 4. Surrounding this gear 27 is a casing 28, made in two halves bolted together for the purposes of assembling. This gear casing 28 is journaled on the pony truck axle 4 so that the axle may turn while the casing remains stationary. An upstanding bracket 29 is bolted to this casing 28 and has sliding fit with a hole in the outer end of an L-shaped brace 30 which is bolted to the journal 3 for the pony truck axle. These parts hold the gear casing 28 from turning. The gear casing 28 is provided with bearings for a vertical shaft 31, to which is fixed a spiral gear 32 meshed with the gear 27. The casing 28 is in practice packed with a suitable lubricant, screw plugs being provided for filling and draining this casing.

The rotation of the vertical shaft 31 is communicated through a suitable universal and telescoping connection to a driven shaft 33 journaled in the inner mechanism casing 18, as shown in Fig. 4. In the construction illustrated, the vertical shaft 31 is connected by an enclosed universal joint 34 of the usual construction to a lower intermediate shaft 35, preferably tubular, which has a telescoping driving connection to an upper intermediate shaft 36, in turn connected by a universal joint 37 to the driven shaft 33. This driven shaft 33 is protected by a hollow boss 38 integral with the bottom of the outer casing 10 (see Fig. 1), and is journaled in a bearing sleeve 39 (Figs. 3 and 4) within a hollow boss 40 integral with the bottom of the inner casing 18. Thus, the upper end of the driven shaft 33 follows the movement of the inner casing 18, and to accommodate this movement and keep out dirt and other foreign matter, a diaphragm or packing is preferably employed between the boss 38 and said shaft 33. It will be evident that the telescoping and universal connection between the shafts 31 and 33 accommodates the vertical and lateral movement of the pony truck axle with respect to the frame on which the

mechanism casings are mounted, as well as movement of the inner casing 18 upon its cushioning springs.

Speed control apparatus.

This apparatus is all carried in the inner mechanism casing 18. This casing is preferably divided by a vertical partition 19 into two compartments, a gear compartment shown at the left in Fig. 3, and an instrument compartment at the right in Fig. 3. In the gear compartment is a centrifugal speed responsive device, cam operating gearing and its control mechanism; and in the instrument compartment are various contact units, relays, and the amplifying equipment. These various devices will be described separately.

Speed responsive device.—This device, designed to determine the actual running speed of the vehicle at all times, as illustrated, is of the type disclosed in the patent to Howe No. 1,384,902 of March 23, 1920. This speed responsive device S, sometimes called a governor, is mounted on the upper end of the driven shaft 33. In the particular construction illustrated, an inverted cup or sleeve 43 is secured to the upper end of the driven shaft 33. This sleeve 43, which turns with the rotation of the pony truck wheel, has two pairs of upstanding standards 44, in which are pivotally supported two pairs of centrifuge arms 45 having corresponding ends connected by cylindrical members 46.

Slidably supported on an upstanding shaft 48 which is fixed to the sleeve 43, is a collar 50 having extending horn-shaped cams 51. This sliding collar 50 and cams 51 are forced to the extreme upper position by the compression spring 52, and thereby cause the centrifugal weights 46 to assume a position near the shaft 48. The upper cylindrical members 46 are pivotally supported and thereby form rollers to constitute a substantially frictionless engagement with the cams 51.

The top part of the collar 50 is formed with a circumferential groove in which fits a rotatable ring 53, preferably provided with bearing balls. Near the lefthand side of the mechanism casing (as shown in Fig. 4) is a speed shaft 54, which is pivoted in a bearing 55 in the partition 19 and in suitable bearing bosses 56 (see Fig. 3) in the ends of this casing. Pinned to this speed shaft 54 is a speed arm 57 (Fig. 4), which has a bifurcated end pivotally connected to the ring 53.

The top end of the shaft 48 is supported in a suitable bearing 59, which is fastened to the cross-bar 60, said cross-bar being bolted to lugs 61 extending from the inside of the mechanism casing.

By looking at Fig. 4 it is apparent that rotation of the speed responsive device S causes the outer ends of the centrifuge arms

45 to take a position away from the axis of this device depending upon the speed at which it is driven, this action being due to the centrifugal force acting on these arms 5 and as opposed by the spring 52 acting on them through the horn-shaped cams 51. The shape of the horn-shaped cams 51 is such that the angular displacement of the speed arm 57 is substantially uniform for 10 all changes of speed for which this centrifugal device S has been designed.

Cam operating gearing.—The sleeve 43 on the driven shaft 33 is formed with teeth to constitute a worm 65 (Fig. 4); and this worm 15 65 meshes with a worm gear 66 secured to a shaft 67 (Figs. 3 and 4) extending horizontally along the bottom of the inner casing 18 and supported in suitable bearings as shown. To this shaft 67 is pinned a pinion 70 oper- 20 atively engaging a gear 71 fastened to the shaft 72 pivotally supported in suitable bearings, and having a pinion 73 fastened thereto. This pinion 73 engages the teeth of a gear 74 fastened to a shaft 75 similar- 25 ly supported in suitable bearings, and having a pinion 76 fastened thereto. This pinion 76 is continually in operative engagement with a gear 77 pinned to the driving shaft 78. The driving shaft 78 extends entirely 30 through the gear compartment, and is rotatably supported in a bearing boss 79 of the partition 19 and a bearing 80 in the outside wall of the mechanism casing.

A shaft 84, conveniently designated the 35 low cam shaft, extends entirely through the mechanism casing and is supported in a bearing boss 85 in the outside wall of the casing. This shaft is mounted to turn freely in a long hollow shaft or sleeve 86, which will 40 for convenience be called the high cam sleeve hereinafter. This sleeve 86 is rotatably supported in a bearing 87 in the partition 19, and is limited against endwise movement by the collar 88 and a gear 112.

45 It is proposed to provide means whereby the high cam sleeve 86 may be started when traffic conditions change from clear to caution and continue to turn this shaft to a pre-determined point and maintain it there until 50 traffic conditions are again clear. Similarly, substantially identical means are proposed for turning the low cam shaft 84 from the time that traffic conditions change from clear or caution, as the case may be, to danger until a suitable minimum speed position has been reached and maintain said shaft in such position until traffic conditions change either to caution or to clear. This apparatus 55 may conveniently be called the cam starting and operating mechanism, and since both of these mechanisms are substantially the same only one of them, namely, the high cam mechanism, will be described in detail, the corresponding parts of the other being

given the same reference characters with the 65 distinctive exponent "a."

Cam starting mechanism.—To the driving shaft 78 is fastened a pinion 90 (Figs. 3, 4 and 7), between which and the retaining collar 91 is pivotally supported a gear frame 70 made up of a sleeve 92 and an extending arm 93. This arm 93 carries a gear 94 continually in mesh with the pinion 90, and a pinion 95 continually in engagement with the gear 94. The sleeve 92 of the gear frame is 75 provided with another extending arm 96, which has its ends bifurcated. Projecting from the outside wall of the mechanism casting are lugs 97 which support the back yoke 98 and cores 99 of the high cam starting 80 magnet HCS. On the cores 99 are coils 100 connected and energized in a manner hereinafter described in the operation. The cores 99 are spanned by an armature 101, which is slidably supported on non-magnetic 85 pins 102 projecting from the top of these cores. The middle of the armature is connected to the bifurcated end of the arm 96 extending from the gear frame by a connecting rod 103, this rod being pivotally supported in said bifurcated end by a pin 107. The lower end of this connecting rod 103 is enlarged, and is urged upwardly by a spring 104 surrounding a stud 105 fastened in the boss 106 extending from the bottom 90 of the casing. To the high cam sleeve 86 is fastened a large gear 108, which is provided with a mutilated portion 109, and is rigidly held in place on this sleeve 86 by a set screw 110, or the like. This gear 108 100 is disposed directly over the pinion 95, and is adapted to be turned thereby when this pinion is in its operative or raised position.

With the railway vehicle equipped with the apparatus thus far described and moving 105 along the track, the speed responsive device S is continually rotated and drives the driving shaft 78, and likewise the pinion 95 through the chain of gears heretofore described. Under normal clear traffic conditions, as hereinafter described, the coils 100 of the cam starting magnet are energized. If the coils 100 are now for any reason de-energized, the attraction between the cores 99 and armature 101 ceases, and the spring 110 moves the arm 96 upward, thereby causing engagement between the pinion 95 and the mutilated gear 108. As the train proceeds along the track, this mutilated gear 108 is rotated until the pinion 95 assumes 115 a position in the mutilated portion 109, after which no further rotation of the mutilated gear 108 takes place and the gear is maintained in this position until the pinion 95 is again brought out of engagement with 120 the mutilated gear 108. If for any reason the coils 100 are again energized, the pinion 95 will be retracted from the mutilated gear 125

108, whereby this gear is again returned to its initial position as shown in Fig. 4 by suitable cam restoring means presently to be described.

5 *Cam restoring mechanism.*—A pinion 112 is fastened to the high cam sleeve 86 by a set screw 113 (Figs. 3, 5 and 6). Directly below this pinion 112 and projecting from a boss on the partition 19 of the mechanism 10 casing is a journal pin 114 secured by a cross pin 117. Pivoted supported on this pin is a gear sector 115, having an extending lug or foot 116 provided with curved ends which are adapted to be engaged by initially tensioned spring devices provided with stops. These spring devices comprise striking blocks 118 and 119, having overlapped extensions also pivoted on the pin 114 and retained in place by a washer 120 secured by 15 a cross pin 121. These striking blocks have their ends resting on bosses 122 and 123. The bosses 122 and 123 are of such a height that the striking blocks 118 and 119 when resting on the bosses just contact with the 20 curved ends of the foot 116 of the gear sector. In the striking blocks are provided holes to receive upstanding guides 124 and 125, which are provided with compression springs 126 and 127 having their lower ends 25 resting in countersunk portions in the striking blocks. The springs 126 and 127 are initially tensioned and maintained in this condition by heavy washers 128 and 129 fastened by cross pins 130 and 131.

30 By looking at Fig. 5 it is readily apparent how the cam restoring mechanism can urge the high cam sleeve in a predetermined position and maintain it there while the cam starting magnet HCS is energized, regardless of whether or not the pinion 95 is rotating at the time. To make this more clear, let us assume that the gear sector 115 has 35 been moved to one of its extreme positions by the pinion 112. Under this condition, either the spring 126 or 127, as the case may be, will be further tensioned because the curved ends of the foot 116 lift up the striking block under this particular spring, thereby further compressing the spring, all of 40 which does not affect or change the tension of the other spring because it is resting on its upstanding boss.

If the high cam sleeve 86 is now released 45 and the pinion 112 is free to turn, the tension of the compressed spring will force its corresponding striking block 118 or 119 downward against the boss 122 or 123, thereby returning the gear sector 115 to its normal position as shown in the drawings. In 50 other words, if the gear sector 115 is moved back and forth from its normal position as shown, first one and then the other of the striking blocks 118 and 119 will be lifted from their respective seats and will compress 55 the corresponding spring, and when this

sector 115 is released it will again return to its normal position.

The cam starting mechanism and cam restoring mechanism, just described, are those associated with the high cam sleeve 86, and 70 are adapted to turn this sleeve when traffic conditions demand its turning, and again return it to its normal position when traffic conditions clear up. Similar apparatus is provided in the lefthand part of the gear 75 compartment shown in Fig. 3 for operating the low cam shaft 84. The parts of the cam starting magnet and cam restoring mechanism for the low cam shaft 84 are substantially the same and have been given the same 80 reference characters as those just described with the distinctive exponent "a."

The gear compartment of the mechanism casing containing the governor, cam starting and cam restoring mechanism is preferably 85 filled with oil so that this apparatus always will be lubricated and protected from moisture and other detrimental agencies.

Contact units.

90

In the instrument compartment above mentioned are contained a number of contact units of different types and performing different functions. These contact units are operated or controlled by the speed shaft 54, the low cam shaft 84, and the high cam sleeve 86, these shafts extending from the gear compartment through the partition 19 into the instrument compartment, as shown in 100 Fig. 3. Since the gear compartment contains lubricant and it is desirable to keep this lubricant out of the instrument compartment, suitable means, such as felt packings, is preferably provided at the points where these shafts pass through the partition. 105

There are a number of these contact units, many of which are constructed the same and differ from each other only in the shape or size of parts. For convenience in explanation, these units are divided into types according to their structure or function; and these distinctive types will now be separately described.

5 *Speed-distance contact unit.*—This unit is intended to open and close certain contacts 115 depending upon the correlation of the existing speed of the vehicle and the distance it has traveled from a certain initiating control point. Generally speaking, this unit is designed to determine the relative position of the speed shaft 54 and the cam shaft 84 or the cam sleeve 86, as the case may be.

Fig. 8 shows one of these speed-distance units as applied to the high cam sleeve 86, a plan view of this same unit being shown 120 in Fig. 3. A specially shaped plate, herein called the high cam H, is fastened to the sleeve 86 by a set screw 135 or equivalent means. The shape of this cam H depends 125 upon a number of factors which are more 130

conveniently discussed hereinafter. To the speed shaft 54, which as hereinbefore explained is turned to different positions by the speed responsive device S, is fastened a speed arm 136 extending downwardly at one side of the cam H. In the lower end of this arm 136 is fixed a pivot stud 137, and on this stud is pivotally connected the lower end of a floating lever 138. The upper end of this floating lever 138 carries a freely revolvable roller 139 which bears against the outer edge of the cam H.

It will be observed that the lower end of the floating lever 138 assumes different positions corresponding to the actual speed of the vehicle at that time, and that the upper end of this floating lever assumes different positions depending upon the shape of the cam H and its position. The middle point of the floating lever 138, therefore, takes a position corresponding to the combined action of speed and cam position. The remaining parts of this speed-distance contact unit are designed to open and close certain electrical contacts when the middle point of the floating lever 138 assumes a predetermined position.

Extending lengthwise of the instrument compartment is a sector supporting shaft 134; and mounted to turn on this shaft is a double contact operating sector Sr consisting of a sleeve 140 and two sector shaped plates 141 and 142 integral therewith and each counterweighted and balanced (see Figs. 8 and 9). A connecting link 143 is pivotally connected at one end to the middle point of the floating lever 138 and at its other end to this contact operating sector Sr, so that as the middle point of this floating lever shifts to the left from the position shown in Fig. 8, this sector is rocked clockwise. A torsion spring 144 on the shaft 134 (see Fig. 3) is fastened at one end to the sector Sr and at the other end to a collar 145 fixed on said shaft. This spring 144 exerts a pressure tending to move the sector Sr counter-clockwise, and in addition to taking up all lost motion, holds the roller 139 tight against the edge of the cam H.

Referring to Fig. 8, a segmental plate 146 having its outer edge formed with two arcuate portions connected by a cam incline 146^a, is adjustably supported on the sector plate 141 by screws 147 passing through slots 148 in said plate. By adjustment of this plate 146, the cam incline thereof may be shifted to assume the desired angular relation with respect to the sector 141, for the purposes hereinafter explained.

Extending along the wall of the instrument compartment is a contact supporting shelf or bracket 150; and on this shelf are supported a number of pairs of movable contact fingers, some normally open and some normally closed. The construction of

these fingers, and their manner of support, is similar, and an explanation of one pair will suffice for all.

Referring to Fig. 8, a pair of normally closed contact fingers 151—152 are shown which are operated by the plate 141 of the sector Sr. Generally speaking, these contact fingers are pivotally supported at their lower ends and are spring pressed in one direction against stops, the distance between one finger and its stop being greater than that of the other finger, so that as one finger is rocked back and forth the contacts on the upper ends of these fingers are separated or brought together. In the particular construction illustrated, each of the contact fingers 151 and 152 is formed with spaced integral ears at the lower end which are pivotally connected by a suitable pin or stud to a supporting standard 153. The standard 153 has a bolt-like extension 153^a which passes through an insulating sleeve 154 in the bracket or shelf 150 and is clamped between two blocks 155 of insulating material by nuts 156, this extension and said nuts constituting a convenient binding post for the attachment of wires. The standard 153 has an upright portion substantially parallel with its corresponding contact finger; and fixed in the upper end of this portion is a pin or stud 157 which passes through a larger hole in said finger. On the pin 157 is a compression coil spring 158, located between the contact finger and a washer 159 on said pin, said washer being held in place by a small cross pin, or the like. When the contact fingers 151 and 152 are pressed together, as shown, the left hand finger 151 is at a greater distance from the upright extension of its standard 153 than is the case with the other finger 152. The fingers 151 and 152 have suitable cooperating contacts at their upper ends, one of these contacts being preferably of non-fusing or refractory material, such as carbon, while the other contact is of high grade silver, or the like.

In the arrangement shown, the carbon button 160 is fixed in a cup having a stem adjustably connected to the upper end of the finger 151, while the resilient silver tip 161 is riveted to the upper end of the finger 152. The lefthand finger 151 has secured thereto, as by rivets, a U-shaped bracket or hanger 162 which has a roller 163 journaled in its outer end and bearing against the edge of the segmental plate 146. Either the roller 163 or the hanger 162 is made of suitable insulating material so as to insulate the finger 151 from the sector Sr.

When the sector Sr is turned clockwise, as shown in Fig. 8, far enough to bring the cam incline 146^a on the plate 146 opposite the roller 163, the contact finger 151 is shifted to the left by its spring 158 until arrested

by engagement with its standard 153; but since the finger 152, as previously explained, cannot move as far, the contacts at the upper ends of these fingers are separated and the circuit therethrough is broken. When the sector is turned again counter-clockwise, the roller 163 is forced to the right, bringing the contacts of the fingers 151—152 again into contact and reclosing the circuit.

10 The contact fingers 174 and 175 in Fig. 9 are constructed and supported the same as the fingers 151 and 152 in Fig. 8, but the segmental plate 176 is so shaped as shown, and the parts are so proportioned, that these fingers 174—175 have their contacts normally separated and are closed when the sector Sr is moved clockwise to the position where the roller 163 is forced toward the right. By comparison of Figs. 8 and 9 it will be noted that the segmental plates 146 and 176 are shaped so that as the sector Sr is moved clockwise, the fingers 174 and 175 close their contacts before the fingers 151 and 152 open their contacts, this difference being variable by adjustment of these plates. In other words, the normally open contacts of Fig. 9, suitable for use for the control of a warning signal, for example, are closed at a lower speed limit or after a less distance 30 of travel than that required to open the contacts shown in Fig. 8, the latter being suitable for governing a brake-setting appliance, for example. In short, by properly proportioning or adjusting the parts, the contact construction shown in Figs. 8 and 9 may be adapted to open or close circuits for any desired predetermined position of a cam and speed arm.

40 *Distance contact unit.*—In Fig. 10 is shown a typical arrangement of contacts which are opened after a predetermined distance of travel of the train following the initiation of one of the distance measuring or cam shafts. The contact fingers are constructed the same as previously described, and may be normally open as shown or may be normally closed.

50 To the lefthand contact finger 167 is fastened a U-shaped hanger 169 which is pivotally connected to a link 170, the other end of which is pivotally connected to a rock arm 171 journaled on the sector supporting shaft 134. The upper end of the rock arm 171 is bifurcated and carries a freely revolvable roller 172 which bears against the edge of a disc 173 secured by a set screw or the like to the high cam sleeve 86. The disc 173 has a portion of its periphery cut away, leaving two inclined shoulders 173¹. It will be evident that as the high cam sleeve 86 is turned in either direction from the normal or initial position to a predetermined extent, one or the other of the shoulders 173¹, depending upon the direction of rotation of the disc 173, strikes the roller 172

and shifts the rock arm 171 to the right to close the contacts of the fingers 167—168. The spacing between the shoulders 173¹ determines the distance of travel required to open or close the contacts. The contact finger 167 is of course insulated, as by making the link 170 of insulating material.

55 *Speed contact unit.*—In Fig. 11 have been shown normally closed contacts 190, 191, 192 and 193, similar to those shown in Fig. 8. These contacts are governed directly by the speed responsive device S and control suitable circuits by breaking them when the speed of the train exceeds a certain amount, which in the particular instance may be assumed to be two miles per hour. The contact finger 193 in this instance has riveted thereto a bracket 194 bifurcated and containing a roller 195. The extreme righthand end of this bracket 194 is similarly provided with a small roller 196, which engages the spring finger 191 engaging the finger 190. The speed shaft 54 has a speed arm 198 pinned thereto and has its free end pivotally connected to a connecting rod 199, which has its other curved end pivotally connected to a sector, conveniently called a two-mile per hour sector and designated 2 m. p. h.

60 This sector 2 m. p. h. has adjustably fastened thereto a cam plate 201, similar to the cam plate shown in Fig. 8. It will be noted that when the arm 198 is rotated clockwise through a small angle, the sector 2 m. p. h. is similarly rotated and causes the roller 195 to ride into the cutaway portion, thereby allowing the contacts 190 and 192 to be moved away from the contacts 191 and 193, respectively, by the action of springs 158. A plurality of speed contacts of this type are provided in this system for opening or closing circuits, as the case may be, at the desired speeds.

65 *Relays.*—Certain of the various relays used in the present train control system are preferably mounted below the shelf 150, and are provided with contacts similar to those heretofore described mounted on and insulated from this shelf. In Figs. 12 and 13 have been shown the push button relay PBR, its purpose and functions to be more fully described hereinafter. This relay comprises a core 204 mounted in a U-shaped member 205 made of soft iron, and supported on a bracket 206 directly below the shelf 150. A coil 207 is held on this core 204 between the pole piece 208 and the member 205. A journal block 209 is riveted to the member 205 for pivotally supporting the armature 210. This armature 210 is shown in its normal attracted position with the coil 207 energized and the armature engaging a non-magnetic residual pin 211.

70 To the top end and above the pivotal support of the armature is riveted an arm 212, having its top end provided with a rivet 213

containing spacing sleeves 214 (see Fig. 13) to maintain the ends of the U-shaped operator 215 adjacent the heads of the rivet 213. The operator 215 of general U-shape 5 has its closed end perforated to receive a guide pin 216. This operator 215 is normally urged toward the right, as shown in Figs. 12 and 13, by a compression spring 217, this spring 217 being held in position 10 on the guide pin 216 by the nut and washer 218. Between the sides of the U-shaped operator 215 is pivotally supported a roller 220 of insulating material, and this roller 220 engages the contact springs 222 and is 15 adapted to complete a circuit by the back contacts 223 engaging contacts 224 when the coil 207 is deenergized, due to the action of the spring 217 urging the U-shaped operator 215 toward the right, as shown in Figs. 12 20 and 13. It should be understood that by a slight modification, front contacts may be provided, that is, contacts which are closed when the coil 207 is energized, instead of back contacts such as illustrated in Figs. 12 25 and 13.

Influence communicating means.

Trackway equipment.—As heretofore mentioned, the present train control system 30 receives its control by a continuous influence transmitted from the trackway to the vehicle, this influence being transmitted by loop circuit current flowing down one rail and back the other as one of the control influences, and by a current flowing in the 35 two rails in multiple and back over a line wire as the other control influence. This manner of transmitting control influences should be kept in mind when considering 40 the trackway apparatus illustrated in Fig. 14.

In Fig. 14 have been illustrated the track rails 228 of the block J and the adjacent ends of blocks I and K of the usual well-known block signaling system having certain additional devices superimposed thereon, the direction of traffic being from left to right as indicated by the arrow. Each of these blocks is equipped substantially the 50 same, and therefore like parts thereof have been designated by the same reference characters with distinctive exponents.

Each of the blocks is provided with a suitable three-position semaphore signal 55 conventionally shown at Z which is controlled by the track relay T of the block at the entrance to which it is located, this control being in part responsive to traffic conditions in the next block in advance by reason of the reversal of the track circuit current by the signal in advance. The operating mechanism, hold-clear devices, and circuits for controlling the signals are omitted to simplify the description of the present 60 invention.

Each of the signals Z is equipped with circuit controllers of well-known construction which have been illustrated in conformity with established convention. According to this invention, the circuit controller is 70 assumed to correspond to a pivoted switch arm shown horizontally by full lines (in alignment with the blade of the corresponding signal) which swings through 90 degrees and completes a circuit through the arc of 75 movement indicated by heavy lines or at the points shown by dots. For example, the circuit controller 242 closes a circuit in the vertical or 90 degree position of the signal, at the inclined or 45 degree position of the signal, and points in between; and this circuit controller also closes another pair of contacts or a circuit in the horizontal or zero degree position of the signal. It may be explained here, without pointing out the 80 specific wiring connections, that the two circuit controllers for the signals Z are in effect pole-changing contacts.

The track relay T of the block J has its track winding under normal clear traffic 85 conditions, as illustrated in Fig. 14, energized by track or loop circuit current supplied from the secondary winding of the transformer 230¹. The circuit for energizing this track winding may be traced as follows:—beginning at the secondary winding 90 of the track transformer 230¹, wire 231¹, the usual impedance 232¹, wire 233¹, track rails 228 of the block J through the track winding of the track relay T back to the other 100 rail 228 of the block J, wire 234¹ back to the secondary winding of the track transformer 230¹.

The primary winding of the track transformer 230¹ is energized by the secondary 105 winding of the transformer 235¹ through a circuit comprising wire 236¹, signal circuit controller 237¹, wire 239¹, primary winding of the track transformer 230¹, wire 240¹, the signal circuit controller 242¹ of signal Z¹, 110 and wire 243¹ back to the secondary of the transformer 235¹. This transformer is energized from the line wires 244 connected to an alternating current generator 245.

It should be noted that if the signal Z¹ 115 at the entrance of the block K changes from the clear to the caution position, the energizing circuit for the track winding of the relay T will not be changed, but if the signal Z¹ moves still further and to the danger 120 position the relative polarity of the track transformer 230¹ is changed due to the reversal of its primary winding by the movable contacts 237¹ and 242¹ operated by the signal Z¹. That is, the current in the track 125 or loop circuit for the block J will flow in the normal direction when the block K in advance is a clear or caution block, but will be reversed when traffic conditions change to make the block K a danger block. 130

In order to supply current in the rails flowing in the two rails in multiple, suitable high resistance shunts have been bridged between the track rails. These resistances will 5 for convenience be called balancing resistances, because current will be fed to or conducted off of the middle point of these resistances, thereby causing the currents to divide between the rails substantially 10 equally. The ohmic resistance of these balancing resistances is preferably so high that their shunting effect on the track relay is negligible. In the particular block J shown only four of these resistances are provided. 15 The section of the block extending from the beginning of the block J or point A to the point B is supplied by a transformer 246. This simplex current flows through the two rails 228 in multiple for the section between 20 points A and B through the following circuit:—beginning at the secondary winding of the transformer 246, wire 247 through the balancing resistance 248, through the two rails 228 in multiple, through the balancing 25 resistance 249, wire 250 back to the secondary transformer 246.

A similar simplex circuit is provided for that portion of the block J shown beyond point B, which is supplied by the transformer 251, and comprises the secondary coil of this transformer, wire 252, contact 253¹ of the track relay T¹, wire 254¹ or 255¹, depending upon whether the block in advance is in a clear or caution condition, wire 30 256, through the balancing resistance 257, through the two rails 228 in multiple, through the balancing resistance 258, wire 259 back to the secondary winding of the transformer 251. It will be noted that this 35 circuit is only broken when the block K in advance is occupied.

Car-carried influence receiving apparatus.—On the railway vehicle, which has been conventionally illustrated by a pair of axles 40 and wheels, are provided suitable laminated magnetic cores for detecting, by magnetic induction, the flow of current in the track rails as shown. These car elements comprise U-shaped cores 260, preferably made 45 of a good quality of laminated iron terminating in enlarged pole pieces 261. These car elements are provided with coils 262. It should be noted that the coils on the front two elements E are wound oppositely so that 50 the voltages induced by currents flowing in opposite directions in the two rails are cumulative, whereas the elements F on the rear of the vehicle have their coils wound alike so that voltages induced in these coils 55 due to current flowing in the same direction in the two rails are cumulative. It is thus obvious that the front coils E will be able 60 to detect loop circuit current, substantially all of which flows through the axles and

does not come under the elements F; where- 65 as the elements F will detect the flow of simplex current which flows in the same direction in both rails in the rear of these two axles illustrated.

The circuit including the elements E and 70 the circuit including the elements F lead to a suitable amplifying apparatus conventionally shown by the rectangle Q. This amplifying apparatus may take various forms, but preferably includes well-known 75 three-element vacuum tubes or audions which amplify the voltages induced in the circuits including these car elements. The current due to the front elements E is amplified and conducted through a winding 263 of the 80 polyphase induction type main relay MR shown, whereas the current flowing due to voltages induced in the car elements F is similarly amplified and conducted through the other winding 264 of this relay MR. If 85 desired, a relay of the dynamometer type may be used instead of the induction type relay MR shown.

As shown in Fig. 14, the vehicle is moving 90 in the block I under clear traffic conditions and the relay is energized to hold its contact 265 in the extreme lefthand position. If the phase relation of the two currents flowing in the windings of this relay MR is reversed, this contact 265 is moved toward the right as indicated by the dotted line 266; and if this relay is deenergized, because one or the other or both of these currents are cut off, the contact 265 will assume the pendent position as shown by the dotted line 267, due to the usual counter-weighting 95 of the relay.

Operation of influence communicating means.—Since the entire trackway through 100 train control territory is provided with both loop circuit and simplex circuit current under clear traffic conditions, the main relay MR maintains its normal energized condition as shown in Fig. 14.

Let us assume now that the block K in advance of the block I is occupied. With this 110 block K occupied by another train, the signal Z¹ at the entrance to this block K assumes its danger position, thereby moving the circuit controllers 237¹ and 242¹ to the 115 position corresponding to the horizontal position of the semaphore. This causes loop circuit current to be fed into the block J by the transformer 230¹ in a reverse direction as compared with what it did when this 120 signal Z¹ was in either the clear or caution position, that is, this transformer 230¹ will now be supplied by current through the following circuit:—beginning at the secondary 125 of the transformer 235¹, wire 236¹, circuit controller 237¹, wire 268¹, primary winding of the transformer 230¹, wire 269¹, circuit controller 242¹, wire 243¹ back to the second-

ary of the transformer 235¹. In practice, the circuit controllers 237 and 242 are parts of a snap circuit controller operated by the signal mechanism, this type of circuit controller being preferred because the circuit would not remain open for an appreciable time which might affect signals in the rear.

With the block K occupied by another train, the track relay T¹ located at the entrance of this block will be deenergized because this relay is shunted by the axles and wheels of said another train. This deenergization of the track relay T¹ causes the contact 253¹ to be in the pendent position, thereby leaving the simplex circuit supplied by the secondary of the transformer 251 open. The reversal of the current in the track or loop circuit of the block J causes the contact 253 of the track relay T at the entrance to this block J to assume the reverse position (shown dotted), thereby moving the signal Z to the caution position by means and in a manner well-known by those skilled in the art.

As the train equipped with the apparatus just described moves through the block I with the block K occupied, the relay MR is maintained in its normal position as illustrated. As this vehicle, however, moves into the block J, this relay MR assumes the reverse position. This is due to the fact that the loop circuit current in the block J has been reversed, as just explained, thereby causing the current in the coil 263 to lag behind instead of lead the current in coil 264 or vice versa, thus reversing the torque in the relay MR and causing it to assume and indicate the caution traffic conditions existing.

Let us assume now that this vehicle passes the point B in the block J. As this point B is passed, the relay MR drops its contact 265 to the pendent or neutral position, because there is no simplex current flowing in the rails 228 beyond the point B. This position of the relay MR may be assumed to be the danger position to indicate that either the simplex or the loop circuit current is entirely absent, due to a train ahead, broken rails, an open drawbridge, or the like.

As the train continues to travel from the block J into the block K (possibly at a reduced speed), the position of the main relay MR will not change. Although simplex current is present in the first section of the block K, no loop circuit current is present because this latter current is shunted through the axles of the train ahead, and does not reach the rear end of the block K.

It should be noted that any change of traffic conditions ahead will be immediately manifested on a following train, because this train is continually receiving current under clear or caution traffic conditions; and

if no current is received in either or both of the windings of the main relay MR, danger traffic conditions are known to exist.

Operation of the system.

Circuit diagram.—In Fig. 15 has been shown a simplified circuit diagram of the car-carried apparatus embodying the present invention. The various relays, speed-distance contacts, distance contacts, speed contacts, cam starting magnets, and the like, have been shown connected in a complete circuit diagram embodying one form of the present invention. In this diagram, the various contacts operated by the various relays are shown directly under each other and connected by a dotted line. Similarly, the speed contacts which are all operated by the same speed shaft, and the distance contacts which are operated by either the high cam sleeve or the low cam shaft, have been shown connected by a dot and dash line to show this relation between certain of the cams. Similarly, the high to medium speed cam H is shown connected to the high cam starting magnet HCS by a dot and dash line, whereas the medium to low cam L is shown connected by a dot and dash line to the low cam starting magnet LCS.

In this circuit diagram, the car-carried apparatus has been shown divided into certain groups. These groups are shown separated by horizontal dotted lines, and in this circuit diagram the several devices have been shown in their normal clear traffic condition with the vehicle running at a speed somewhere between, say, forty miles per hour and the maximum speed that the train is permitted to run without an automatic brake application, which for convenience is assumed to be sixty miles per hour. The various electro-responsive devices may be energized by any suitable source of energy supply available, this energy supply preferably being direct current received from a generator or some other suitable source of supply, a battery 271 having been illustrated for this purpose. As shown, the various devices are connected between the bus wire 272 and the return wire 273, each group of devices being shown maintained electrically independent of the other groups as much as possible for the purpose of simplifying the wiring diagram.

Normal conditions.—The main control relay MR controls repeater relays N and R, which in turn control the various ab signals and car-carried electro-responsive devices. Under the normal clear position of the relay MR, both of these repeater relays N and R are energized. The normal repeater relay N is energized through the following circuit:—beginning at the battery 271, bus wire 272, wires 275 and 276, contact 265 of the main relay MR, wires 277 and 278, wind-

ing of the repeater relay N, wires 279 and 280, return wire 273 back to the battery 271.

The reverse repeater relay R is energized under clear traffic conditions by the front 5 contact of the normal relay N, through a circuit which may be traced as follows:—beginning at the battery 271, bus wire 272, wires 275 and 281, front contact 282 of the normal relay N, wires 283 and 284, winding 10 of the reverse relay R, wires 285 and 280, return wire 273 back to the battery 271.

The relays N and R are preferably slow acting, so that the movable contact 265 of the main relay MR will have assumed its 15 caution position (shown dotted) before the normal relay N has opened its front contact 282, and the reverse relay R has had time to open its front contacts. This slow action is desirable because the reverse relay R 20 would otherwise be momentarily deenergized if the normal relay N should break the energizing circuit for relay R at the front contact 282 before this energizing circuit would again be completed by the movable 25 contact 265 of the main relay MR in its reverse dotted position.

The various positions of the contact 265 of the main relay MR corresponding to the various traffic conditions have been heretofore pointed out. It should now especially be noted that under clear traffic conditions with the contact 265 of the main relay MR in the extreme lefthand position, a circuit for energizing the normal repeater relay N 30 is completed; and with the relay N energized, a circuit for energizing the reverse repeater relay R is completed, thus maintaining both of the relays N and R in the energized position under clear traffic conditions. Under caution traffic conditions, with the relay MR assuming the other extreme position, the relay R only is maintained energized; and with the main control relay MR in the deenergized position, both the 40 normal relay N and the reverse repeater relay R are deenergized. Also, under this the normal condition of the main relay MR, the green cab-signal lamp Gr is lighted as more clearly pointed out under "Cab signals".

Under normal clear traffic conditions, the 50 penalty relay PR (found in the penalty group, Fig. 15) is energized by the following circuit:—beginning at the battery 271, bus wire 272, wires 301 and 302 through the back contact 303 of the reverse relay R in multiple with the cam contact 304 operated by the low penalty cam LP, wires 305 and 306, the front contact 307 of the normal relay N in multiple with the cam contact 308 55 operated by the high penalty cam HP, wires 309 and 310, front contact 311 of the penalty relay, wires 312 and 313, winding of the penalty relay PR, wire 314 back to the common return wire 273 leading to the battery 271.

The high cam starting magnet HCS (cam starter group) is under normal clear traffic conditions energized through the following circuit:—beginning at the battery 271, bus wire 272, wire 315, back contact 316 of the 70 push button relay PBR, wires 317, 318 and 319, front contact 320 of the normal relay N, wires 321 and 322, winding of the high cam starting magnet HCS, wires 323 and 324 back to the common return wire 273 connected to the battery 271. 75

The low cam starting magnet LCS is normally energized through a similar circuit as follows:—beginning at the battery 271, bus wire 272, wire 315, back contact 316 of relay 80 PBR, wires 317 and 325, front contact 326 of the reverse relay R, wires 327 and 328, winding of the low cam starting magnet LCS, wires 329 and 324, through the common return wire 273 back to the battery 271. 85

With the vehicle traveling along the track under normal clear traffic conditions at a speed as heretofore mentioned (above forty miles per hour but below the maximum permissive speed), the electro-pneumatic valve 90 E. P. V. (E. P. V. and warning signal group) is maintained energized through the following circuit:—beginning at the battery 271, bus wire 272, wires 330 and 331, front contact 332 of the penalty relay PR, wires 95 333, 334 and 335, front contact 336 of the reverse relay R, wires 337 and 348, speed-distance contacts 151 and 152 of the high cam H, wires 338 and 339, front contact 340 of the electro-pneumatic valve E. P. V., 100 wires 341 and 342, winding of the E. P. V., wire 343 and common return wire 273 back to the battery 271.

It should be noted that the front contact 336 in the circuit just traced is shunted by 105 partial circuit (wires 344 and 346, contacts 151¹—152¹ of the low cam L and wire 345) including contacts operated by the low speed-distance cam L, so that when the repeater relay R is deenergized this contact 110 336 opens (removes the shunt) and puts these two pairs of speed-distance contacts in series in a circuit including the E. P. V. Under this condition of the apparatus, the E. P. V. will be deenergized to cause an automatic application of the brakes if the speed exceeds that enforced by either of the speed-distance cams H or L; whereas if the contact 336 is closed, the speed limit set up by the speed-distance cam H only is enforced. 115

The electro-pneumatic brake applying means E. P. V. is of the normally energized type, and may take any one of a variety of forms well known in the art. For instance, 120 it may include suitable means for actuating the usual engineer's valve to apply the brakes in a manner so that the engineer is unable to forestall or prevent its taking effect, that is, may actuate the valve handle with a force 125 130

which the engineer is unable to oppose; or actuate the valve itself and simultaneously therewith disconnect the handle from the valve at least as far as operation toward the 5 release position is concerned. Since various devices suitable for this purpose are known in the art, and since the present invention is more particularly directed to means for actuating a brake applying device, this device 10 has been conventionally shown as comprising an electro-pneumatic valve. Similarly, this apparatus may be designed so that it will vent the brake pipe to a predetermined extent only, and if this amount of braking 15 already exists prevent its taking effect altogether.

Thus, under normal clear running conditions, both the high and low cam starter magnets HCS and LCS are energized, both 20 the high speed cam and the low speed cam are in the normal or initial maximum speed position, and the operation of the brake controlling device E. P. V. is dependent on the observance of a maximum speed limit of, say, 25 sixty miles per hour.

Cab signals.—With the main relay MR energized the repeater relays N and R in the clear traffic condition, and the green lamp Gr is illuminated by the following circuit:— 30 beginning at the battery 271, bus wire 272, wires 275 and 276, contact 265 of the main relay MR, wires 277 and 286, green lamp Gr, wires 287, 288 and 289, the return wire 273 back to battery 271.

35 Under caution conditions, the contact 265 of the relay MR is reversed to the dotted position, interrupting the circuit just traced for the green lamp Gr, the reverse relay R being kept energized through the following 40 circuit:—beginning at the battery 271, bus wire 272, wires 275 and 276, movable contact 265 of the main relay MR, wires 290 and 284, winding of the repeater relay R, wires 285 and 280, the return wire 273 back 45 to battery 271. Under the caution traffic condition of the main relay MR, the yellow lamp Y is illuminated by current flowing through the following circuit:—beginning at the battery 271, bus wire 272, wires 275 and 50 281, contact 282 of the normal relay N, wire 291, front contact 292 of the reverse relay R, wire 293, yellow lamp Y, wires 294, 288 and 289, common return wire 273 back to the battery 271.

55 If the main relay MR is deenergized on account of danger traffic conditions ahead, the movable contact 265 of this relay drops to the pendent position, thereby deenergizing both the relays N and R. This causes 60 the lamps Gr and Y to be deenergized, as is obvious from the wiring diagram, and causes the red lamp Rd to be lighted through the following circuit:—beginning at the battery 271, bus wire 272, wires 275 and 281, 65 contact 282 of relay N, wire 291, contact 292

of reverse relay R, wire 295, contact 296 of the relay NS, wire 297, red light Rd, wires 298, 299 and 289, common return wire 273 back to the battery 271.

Maximum speed restriction (car apparatus normal).—With the high speed-distance cam H in the normal position (see Figs. 8 and 15), a certain predetermined speed limit will be set up which if exceeded will cause an automatic brake application. Referring more particularly to Fig. 8, assuming the cam H to remain in its normal position as shown, it is noted (see Figs. 3 and 4) that the speed arm 136 will be moved in a clockwise direction as the speed of the vehicle is increased. This clockwise movement of the speed arm causes the lower end of the floating lever 138 to be moved toward the left, it being fulcrumed by the roller 139 on the high cam H, and moves the link 143 toward the left, thereby rotating the sector Sr in a clockwise direction. Obviously, if the speed is increased to a predetermined value (assumed to be sixty miles per hour), the roller 163 rides down the cam incline of the sector 90 146, thus causing the contacts 151—152 to be opened (see Fig. 15), thereby breaking the stick circuit for the E. P. V. and causing an automatic application of the brakes in a manner as heretofore described. Before an 95 automatic brake application is effected in the manner just described, a suitable warning signal will be operated, as more clearly pointed out hereinafter.

Acknowledgment of caution signal.—Let us assume that a car equipped with the apparatus illustrated in Fig. 15 is moving along the trackway and is just about to pass a signal at caution. If the engineer or operator is aware of this fact and attends to his duties, he will acknowledge this change of traffic conditions by making a manual act in recognition of his knowledge of changed traffic conditions, which in the present embodiment of the invention consists in pressing the push button PB before this change of traffic conditions is manifested by the reversal of the main relay MR. By pushing this button PB, the push button relay PBR is energized through a circuit obvious from the drawings and including this relay and push button, which, among other things, (including the momentary picking up of relays NS and L-Ack) closes the front contact 350 which completes a pick-up circuit for the high speed acknowledging relay H-Ack. This circuit comprises wires 352, 353 and 354, make-before-break contact 351, wires 347 and 412, front contact 350, wires 413 and 358, winding of the relay H-Ack, wires 359 and 360. With this acknowledging relay H-Ack picked up, dropping of the normal relay N causes its make-before-break contact 351 to drop, thereby closing a stick circuit through 110 the acknowledging relay H-Ack and main- 115 120 125 130

taining this relay stuck up through said stick circuit, which may be traced as follows:— starting from the battery 271, bus wire 272, wires 352, 353 and 354, make-before-break 5 contact 351, wire 355, front contact 356, wires 357 and 358, winding of the high acknowledging relay H-Ack, wires 359 and 360 back to the battery 271.

It should be noted that the pick-up circuit 10 for the high speed acknowledging relay H-Ack includes a front contact 351 of the normal relay N. Consequently, unless the push button PB is closed and the relay PBR energized to close its front contact 350 before the normal relay N is deenergized, then 15 the acknowledging relay H-Ack cannot thereafter be energized by operation of said push button. In other words, the push button PB must be operated by the engineer before the normal relay N is deenergized by 20 the control from the trackway. The engineer cannot wait until the indications of the cab signals or indicators change before taking action. He must be alert and watch out 25 for the trackway signals, recognize the caution indication of a signal he is approaching, and operate the push button PB before the relay N responds to the control from the trackway, otherwise he cannot energize the 30 acknowledging relay H-Ack and avoid the penalty hereinafter explained: This arrangement assures that the engineer will keep his attention on the trackway and will watch out for the trackway signals. It is 35 considered that this is important in a train control system, because modern block signal systems are very dependable and if observed and obeyed by the engineer, afford a very high degree of safety of train movement; 40 and if, in addition to the protection afforded by the automatic train control system, there is still retained the safety afforded by the trackway block signals and the care and vigilance of the engineer, the ultimate safety of 45 the train is doubly assured, so to speak, an accident occurring only in the event of failures of the block signals, engineer, and train control system all at the same time.

It also should be observed that, when the 50 push button PB is actuated and the relay PBR energized, the back contact 316 of said relay is opened, and breaks the energizing circuits for the two-cam starting magnets HCS and LCS. Consequently, the push button PB cannot be carelessly or maliciously 55 held or fastened down without detection, since the cam starting magnets would then remain deenergized and impose restricted speed limits in the manner more fully explained hereinafter. This assures that the 60 engineer must operate his push button PB at each trackway signal and cannot hold or fasten it down and avoid acknowledgment of each unfavorable signal indication. It is 65 obvious, of course, that other penalties may

be imposed for holding down the push button PB longer than necessary to acknowledge the signals; and the particular provision indicated is merely typical of an expedient suitable to perform this function. 70

If the engineer fails to see the caution signal and neglects to anticipate the de-energization of the normal relay N by manual manipulation of the push button PB so as to energize the acknowledging relay 75 H-Ack, the front contact 361 of said acknowledging relay remains open, and with contact 307 opened upon deenergization of the relay N, the stick circuit for the penalty relay PR is dependent upon the closure of 80 the contacts 308 of the high speed penalty distance contact unit HP. When the normal relay N is deenergized, as just explained, its front contact 320 shown in the "cam starter group" will also break its circuit, 85 thereby deenergizing the high cam starting magnet HCS. The deenergization of the high cam starting magnet HCS causes the gear 95 to engage the mutilated gear 108, thereby causing this gear to be rotated by a 90 chain of gears driven by the drive shaft 78 and in turn causing gradual rotation of the high cam H. Shortly after the high cam H begins on its operating cycle, the high penalty cam HP, which is connected to the 95 same sleeve 86, allows the roller of the contact 308 to ride off the cam surface, thereby opening this contact. Likewise, the dropping of the relay N opens the front contact 307 (penalty relay group); and if the high 100 acknowledging relay H-Ack is not then energized to complete a shunt around these two contacts just mentioned (307 and 308) by the front contact 361, wires 362 and 363, the penalty relay PR has its stick circuit 105 broken and is permanently deenergized. If, however, the acknowledging relay H-Ack has been picked up by the manual operation of the push button PB, and is stuck up through its stick contact, the penalty relay 110 remains energized, and the opening of the two contacts (307 and 308) in multiple with the contact 361 (which is now closed) produces no effect under these conditions. 115

It may be explained that the contacts 308 of the high speed penalty distance unit HP are employed to avoid deenergization of the penalty relay PR in the case of a momentary deenergization of the normal relay N, due to a temporary failure of the controlling influence from the trackway. As already explained, the main car relay MR is maintained energized with its contact finger in the normal or reverse position only so long as there is a signaling or train controlling 120 current flowing in both the loop and simplex circuits in the track rails, and that as soon as the car fails to pick up either loop or simplex current, this main control relay is deenergized and causes the normal and re- 125 130

verse relays N and R to drop their contact fingers. In applying this scheme of continuous inductive control to practical railway conditions, it is found it may not be 5 always practical or expedient to maintain a continuous supply of signaling current to the track rails. For example, at crossings, crossovers, block entrance, and the like, there 10 may be a short distance of travel of the locomotive or other vehicle during which the receivers are not picking up either loop or simplex circuit current, and it may not be expedient to provide a substitute for such current by the use of wave wires, or the 15 like.

While the main car relay MR has, of course, a limited time lag of operation, and the relays N and R may also be made slow acting, it is thought that certain situations 20 may arise where the relays N and R may be deenergized, due to the failure to receive signaling current, for a short distance of travel; and unless some provision is made, this would result in deenergization of the 25 penalty relay PR and the infliction of the penalty in spite of the fact that the engineer would not be at fault and should not be expected to operate the push button PB at each of these points on the trackway where 30 such a situation may exist. Accordingly, the distance operated contacts 308 are provided, so that the penalty relay PR is not deenergized upon dropping of the relay N and failure of the engineer to acknowledge 35 in those cases where such deenergization of the relay N is only temporary and for a short distance of travel. This arrangement assures that the locomotive may pass over the "dead sections" without a brake application or infliction of a penalty for failure 40 on the part of the engineer to take an acknowledging action. The same explanation and the same reasoning applies to the distance contacts 304 of the low speed distance 45 contact unit LP, which is in multiple with and may be shunted by the contact 364 of the relay L-Ack.

From the foregoing it will be appreciated that the penalty relay PR is deenergized at 50 each caution signal, unless the engineer acknowledges the signal by taking the appropriate action. Obviously, the engineer will not do this unless there is some sort of a penalty for his failure to do so. Accordingly, it is proposed in this system to impose a suitable penalty, in the form of annoyance or trouble to the engineer, when 55 the deenergization of the penalty relay PR indicates a neglect on the part of the engineer to observe and acknowledge a caution 60 signal indication.

Generally speaking, this penalty consists in automatically applying the brakes upon deenergization of the penalty relay PR, un-

less the speed of the train is then below some 65 low speed, such as fifteen miles per hour, and maintaining such application until the speed has been brought below this limit and the engineer by a positive act of operating the push button PB restores the brake control valve E. P. V., whereupon the train may proceed at a speed under this low speed limit of fifteen miles per hour but no faster until brought substantially to a stop so as to reset the penalty relay PR, all as explained 70 more in detail hereinafter under "Penalty for failure to acknowledge".

Speed restrictions—high to medium.—The steps of operation thus far considered, briefly stated, comprise the movement of the train 80 from clear territory into caution territory:— (1) when the engineer makes an anticipatory acknowledgment; and (2) when he does not make such an acknowledgment. In any event, the high speed cam starting magnet 85 HCS is deenergized and gears the high speed cam sleeve 86 to the wheels, so that this sleeve is driven from the normal or initial position in one direction or the other, depending on which end of the locomotive or 90 other vehicle is leading, gradually and at a rate corresponding to the rotation of the car wheels and the distance traveled. In short, the cam H, Fig. 8, is turned gradually clockwise or counter-clockwise, as the case may be, 95 from the position shown in accordance with the distance traveled; and each degree of rotation of this cam corresponds to a certain number of revolutions of the car wheels and a certain increment of distance traveled. 100

The shape of the cam H determines a varying permissible speed limit which, if at any time exceeded, results in an automatic brake application. There are a number of factors determining the particular shape of the cam suitable for practical operating conditions. Generally speaking, this cam is so shaped that, in cooperation with the speed arm 136, it causes operation of its controlled contacts whenever the train exceeds a pre-determined speed for corresponding points in its travel after the cam has been geared to the wheels, these speed limits at the various points along the track corresponding to a particular speed-distance curve. Such a speed-distance curve of limiting or permissible speed is arbitrarily determined with reference to the braking power of the train to be equipped, due regard being paid to the factors of braking power, grade, and the like. The exact shape of the cam depends upon the position assumed by the speed arm 136 and associated parts for the varying actual speeds of the car. It is convenient, however, to look upon the cam as having its various radii proportionate in length to the ordinates of a permissible speed curve which it is desired to re- 115 120 125

produce; and for simplicity the cam will be treated as a device for determining a permissive speed limit which if exceeded results in an automatic brake application.

5 The cam is preferably made symmetrical, as shown, so that it produces the same movement of its follower when turned in either direction from its initial position, this expedient being adopted so that the same permissive speed is prescribed, regardless of the direction of rotation of the car wheels, and thereby permitting a locomotive to run with either end leading without requiring any adjustment or change. The periphery of the 10 cam varies in radius throughout an angle corresponding to the distance of travel during which the desired change in speed limits are to be obtained, the remaining portion of the periphery of the cam being concentrical 15 with its axis of rotation, so that although its operating shaft or sleeve is turned through a greater angle, the same speed limit is maintained.

As already mentioned, the system of this 20 invention employs two cams, one controlling from a maximum speed of, say, sixty miles per hour, to an intermediate or medium speed of, say, forty miles per hour, and the other from the medium speed to a minimum speed of, say, fifteen miles per hour.

Assuming that the high cam H is constructed in accordance with the principles just explained, when the high cam starting magnet HCS is deenergized at the caution 25 signal, or corresponding control point, and the high cam sleeve 86 is geared to the car wheels through the reduction gearing previously explained, as this cam H turns (see Fig. 8) its radii increase and shift the roller 139 more and more to the left. If the train 30 is traveling at a speed somewhere near the maximum speed of sixty miles per hour, the speed arm 136 stands at a position considerably further to the left than shown in Fig. 8, so that the sector Sr is turned to the point 35 where the roller 163 is almost opposite the cam incline on the plate 146. Visualizing these positions, it can be readily seen that as the cam H turns, shifting the upper end of 40 the floating lever 138 further to the left, the actual speed of the vehicle must be correspondingly reduced to move the speed arm 136 and the lower end of the floating lever 138 more to the right to a corresponding extent, 45 otherwise the middle point of this floating lever is moved so far to the left as to open the contacts of fingers 151 and 152. Consequently, if the train enters the caution block 50 at high speed, the engineer must apply the brakes and reduce this speed in order to 55 avoid the automatic opening of the contacts of fingers 151 and 152. In short, the engineer must keep the actual speed of his train 60 below the imaginary speed-distance curve 65 of the permissive speed prescribed by the

cam as it moves. Putting it another way, the engineer may run his train at any speed so long as he keeps below the cam curve of permissive speed. For example, he may enter the caution block at a speed of, say, 70 fifty miles per hour, and run some distance into the block before applying the brakes.

After the cam has turned through a certain angle corresponding to a certain distance of travel, its maximum radius is opposite the roller 139 and the intermediate or medium speed limit of forty miles per hour is set up and remains in force until the cam is automatically restored. When the cut-away portion of the mutilated gear 108 driving the high cam sleeve 86 comes opposite the driving pinion 95, further rotation of the cam ceases; and although the train may continue to travel, the cam sleeve 86 and the cam H remain stationary in this medium speed position. The cam H may be shaped to reach the medium speed position before the mutilation in the gear 108 comes opposite the pinion 95, or at about the same time according to the wishes of the designer and dependent upon the way in which it is found most expedient to overlap or separate the cam curves.

The net result of the operation just described, that is, starting the movement of the high cam H, results in compelling the train to reduce speed, if necessary, and in any event keep below a predetermined permissive speed curve. It will be evident that this permissive speed cam curve may be determined in such a way that, so long as the train keeps its speed below this limit, it is being governed safely, and if these varying speed limits are exceeded at any time, a brake application is necessary in order to 105 stop the train short of point of danger.

Restoring speed control apparatus in a caution block.—One of the important features of this invention is that as soon as traffic conditions change ahead and become 110 more favorable, the speed control apparatus is automatically reset or restored, relieving the train from the speed limits and permitting it to accelerate.

Shortly after the train in question has 115 entered a caution block, suppose the block next in advance becomes unoccupied. Obviously, it is no longer necessary for the following train to reduce speed, since there is at least one whole block in advance available 120 for stopping. It is permissible and desirable, therefore, to reset the cam H as soon as this block next in advance becomes unoccupied.

Referring to the trackway equipment of Fig. 14, suppose that the train in question is 125 in the block J and has had its cam H set into operation upon entering this block, because there is another train in the block K, and suppose further that the train ahead leaves the block K. The track relay T¹ is 130

at once energized, and the signal Z^1 automatically assumes the caution or clear position, depending upon the new location of the train formerly in the block K. In either 5 case, the circuit controllers 237¹ and 242¹ of the signal Z^1 change and apply loop circuit current of the normal polarity to the block J. The car relay MR on the following train 10 at once responds, shifting its contact finger 265 to the normal position (shown in full lines in Fig. 15). The normal relay N is, therefore, energized and in turn energizes the high cam starting magnet HCS, disengaging the pinion 95 from the gear 108, 15 and permitting the high cam sleeve 86 to be restored to the initial position by the restoring mechanism, as previously explained. Also, the cab signal indications are changed from yellow or caution back to green or 20 clear. The back contact 351 of the relay N opens and breaks the stick circuit for the high speed acknowledging relay H-Ack, the contact 307 closing at the same time to maintain the penalty relay PR energized irrespec- 25 tive of the opening of the front contact 361 of the relay H-Ack. In this way, the various parts and circuits are restored to the normal conditions that exist under normal clear running conditions.

30 *Acknowledgment of danger signal.*—Proceeding with the operation on the assumption that the block in which the train is running is still a caution block (the next block in advance still being occupied) at the time 35 said train reaches the point B, by looking at Fig. 14, it is noted that the simplex circuit is interrupted at the contact 253¹ of the track relay T¹, and that the main relay MR therefore will be deenergized upon 40 movement of the train by the point B. To avoid being penalized, the engineer will be required to acknowledge the change of traffic conditions in a manner corresponding to that necessary when a change of clear to caution 45 took place. This is accomplished by pushing the same push button PB, although an entirely different group of circuit changes are effected.

First, assume that the engineer does push 50 this push button PB in time to anticipate the deenergization of the main relay MR, which takes place upon movement of the train by the point B. The actuation of the push button PB energizes the push button 55 relay PBR, thus closing the contact 375 and completing a pick-up circuit for the low acknowledging relay L-Ack as follows:—beginning at the bus wires 272, 352, 376 and 377, front make-before-break contact 378, 60 wires 379 and 380, front contact 375 of the push button relay, wires 381 and 382, acknowledging relay L-Ack, wires 383 and 360 to the common return wire 273.

With the acknowledging relay L-Ack 65 picked up, the dropping of the reverse con-

trol relay R causes its make-before-break contact 378 to drop and complete a stick circuit for the relay L-Ack before it breaks the pick-up circuit just traced. This stick circuit comprises main bus wires 272, wires 70 352, 376 and 377, make-before-break contact 378, wire 384, stick contact 385 of the relay L-Ack, wires 386 and 382, winding of the relay L-Ack, wires 383 and 360 and common return wire 273. This make-before-break 75 circuit change causes the relay L-Ack to remain energized and the contact 364 controlled thereby closed until the relay R is again energized.

The dropping of the reverse relay R also 80 changes the position of the contact 292, thus changing the signal from caution to danger, and also opens contacts 303, 326 and 336. The opening of contact 326 breaks the circuit for the low cam starting magnet LCS, 85 thus initiating movement of this low cam L; the opening of the contact 336 breaks the shunt around the contacts 151¹—152¹ governed by the low cam L, thereby causing enforcement of a permissive speed set up by 90 this low cam L (the contacts 151¹—152¹ of the two speed-distance cam units being in series); and the opening of contact 303 removes a shunt around the contact 304 controlled by the low penalty distance contact 95 LP. After a very short distance of movement of the train, after the low cam L has been initiated, the contact 304 controlled by the distance cam LP (operatively connected 100 with the low cam L) opens. Since, however, the low acknowledging relay L-Ack has been picked up and the contact 364 closed, as heretofore explained, the opening of the contacts 304 and 303, both of which are in 105 multiple with the contact 364 of the low acknowledging relay L-Ack, produces no effect, that is, the penalty relay PR is maintained energized and unchanged.

Speed restrictions—medium to low.—As 110 the train or vehicle moves along the track, bearing in mind that the high cam H has been run to its lowest permissive speed position, both of the acknowledging relays H-Ack and L-Ack are energized and stuck 115 up by their respective stick contacts, the low cam L is initiated, and the contact 336, normally shunting the low speed-distant contacts 151¹—152¹, is open. Consequently, the low cam L will set up gradually decreasing 120 speed limits which require a corresponding decrease in the speed of the vehicle to avoid an automatic brake application as the vehicle proceeds in the block beyond the point B, such automatic application of the brakes being effected by the opening of contacts 125 151¹—152¹ of the low speed-distance cam L in this particular instance. The speed limits set up by the low speed-distance cam L are enforced substantially in the same manner as those set up by the high speed- 130

distance cam H, as heretofore described.

After the train has moved a certain distance, which in practice is such that the low speed cam L has reached its ultimate position, because the pinion 95^a has reached the mutilated portion of the gear 108^a, a low limiting or minimum speed limit is enforced, which for convenience is assumed to be fifteen miles per hour. With the apparatus in this condition, and with this minimum speed limit of fifteen miles per hour set up, the engineer will be compelled to keep his speed below this value to avoid an automatic brake application in a manner as heretofore pointed out.

Reviewing the operation, it should be noted that a normal high speed of, say, sixty miles per hour is enforced under clear traffic conditions, that this speed restriction is gradually reduced under caution traffic conditions until a constant medium speed of, say, forty miles per hour is enforced, and thereafter, when passing the point B in a caution block, another series of gradually reducing speed limits are enforced until a low limiting or minimum speed limit of, say, fifteen miles per hour is enforced.

Occupied block control.—The minimum or low speed limit of fifteen miles per hour continues indefinitely until the car relay is energized. As previously explained, in order to energize the main car relay, it is necessary to pick up both simplex and loop circuit current. Referring to Fig. 14, and assuming a train somewhere in the block K, it will be observed that the loop circuit current in the track rails of the block is shunted by the wheels and axles of the train and does not flow in the track rails behind that train. Consequently, if a following train enters this occupied block K, it can pick up no loop circuit current, and even though the simplex circuit current is flowing in the track rails (back of the point B at least), the main car relay is not energized and the minimum speed restriction continues in force. Thus, this system provides a restricted minimum or low speed limit in an occupied or danger block. Also, the enforcement of this minimum speed limit depends upon the flow of current in the track rails, so that if these track rails are shunted by another train, or a track rail is broken, a drawbridge open, or other hazardous condition exists, the minimum speed limit persists independent of any control by the regular track relays.

Restoring speed control apparatus in a danger block.

(1) *In rear of point B.*—With the train moving in a danger block, that is, in the rear of another train in the same block at this low restricted speed limit of fifteen miles per hour, let us assume that the other train ahead moves out of the block before the

train in question reaches the point B of this block, that is, the section now occupied by the train is a caution section, and a danger to caution change has just taken place. This change causes the contact of the main control relay to move to the dotted position 266, thus again picking up the reverse repeater relay R. The re-energization of the reverse relay R again lights the yellow lamp and extinguishes the red lamp, breaks the stick circuit of the low acknowledging relay L-Ack by picking up the make-before-break contact 378, thus deenergizing this relay, and closes the contacts 303, 326 and 336.

A sequence of operation takes place when this reverse relay R picks up which should be carefully considered. It should be noted that the closing of contact 326 energizes the low cam starting magnet LCS, and that a short time thereafter the contact 304 is closed because the low cam L will, by the action of the cam restoring means (see Fig. 5), be brought back to its initial position. Since, however, the make-before-break contact 378 is immediately brought to its raised position and breaks the stick circuit for the acknowledging relay L-Ack, the back contact 364 opens immediately and before the contact 304 can possibly again close, the penalty relay would be deenergized were it not for the contact 303. That is, had the contact 303 been omitted from the system, the contact 364 would have caused the stick circuit for the penalty relay PR to be broken, because the contact 364 was broken immediately upon the re-energization of the relay R; whereas a considerable lapse of time was necessary for the contact 304 to close, since this contact 304 does not reclose until the cam mechanism has been returned by the cam restoring apparatus. In other words, the contacts 303 and 304 as connected and by their inherent characteristics as a result of being quick and slow acting, respectively, afford a means for causing a quick making of a contact due to the energization of the relay R and a slow breaking of a contact upon deenergization of this relay R. This operation of the contact mechanism causes a shunt to be quickly established around the contact 364 of the relay L-Ack upon energization of the reverse relay R, and causing a shunt around this contact 364 to be temporarily maintained when this relay changes to its deenergized position.

(2) *In advance of point B.*—If the train in question is very closely behind the other train heretofore mentioned and has already reached a point beyond the point B before the other train moves out of the block J in question, the car-carried apparatus is left unchanged, that is, is still enforcing a minimum continuing speed limit as heretofore. This is because the following train is occupying the section beyond the point B and

is deprived of the flow of current in the simplex circuit, the track relay T^1 of block K being deenergized and its contacts open due to the presence of the forward train in the block K.

- As the train ahead passes from the next block K ahead into the next succeeding block, the traffic conditions for the section occupied by the following train (beyond point B in block J) change abruptly from danger to clear. Under this condition, the contact 265 of the main relay MR moves directly from the pendent to the normal left-hand position (as shown in the drawings), thus energizing both the normal relay N and the reverse relay R. This change of these two relays N and R from their deenergized to their energized condition, respectively, causes the green lamp to be lighted, restores both of the speed-distance cams L and H, and then deenergizes both the acknowledging relays L-Ack and H-Ack. In other words, it brings the system back to its initial normal condition.
- Particular notice should be taken of the fact that the automatic restoring operation occurring in an occupied or danger block, as just described, is dependent upon the flow of signaling current in the track rails, and is wholly independent of the condition of the track relay of the block next in advance. Consequently, such automatic restoration in a danger block can take place only if such restoration is safe and proper. For example, if there is a broken rail, or a car on the fouling point of a switch, or other hazard in a block, a train entering that block must proceed at the minimum speed limit until such hazard is reached or removed, in spite of the fact that the next block in advance may be safe and unoccupied. This control, it will be noted, accords with the practice commonly demanded by the operating rules of most railroads which require a train to travel at restricted speed prepared to stop within vision throughout the length of a danger block, even though the signal next in advance can be seen and indicates clear or caution. The automatic inductive control of this invention compels adherence to this operating rule, and goes further by permitting restoration of the speed control apparatus and acceleration of the train if and as soon as the danger conditions are removed, the existence of such danger conditions being dependably determined automatically by virtue of the flow of loop circuit current in the track rails, such current flow being dependent not only upon the presence of the car in the block but also upon the continuity of the track rails.

Warning signal.—In the operation of the system thus far described, no specific reference has been made to the arrangement for

giving some kind of a warning to inform the engineer when the speed of the train is approaching the speed limit set up by the apparatus at the time. This warning signal is preferably of the audible type, so that the engineer will not be detracted from watching the roadway ahead and other duties which require his attention. This warning signal was not mentioned in the foregoing description in order to simplify the described operation of the automatic speed restricting apparatus.

In providing such an alarm or warning signal when the actual speed of the train is almost as high as the permissive speed permits, it is desirable to actuate such a signal at such a time that the engineer will be able to control the train to avoid an automatic brake application and still not give such a signal until it is absolutely necessary. In order to keep the engineer from leaning too heavily upon the automatic train control apparatus, so to speak, it is preferable to provide an audible signal when the speed limit set up has almost been reached for the continuing or uniform speed limits set up, that is, for the high, medium and minimum speed restrictions respectively, and no such warning when the cam is being moved and the permissive speed is changing.

In the particular form of the invention illustrated, a warning signal has been shown as comprising an electrically controlled air whistle 390, which is adapted to be operated by contacts 174—175, 174'—175' actuated by sectors 142, 142' directly connected to the sectors 141 of both the high and low cams H and L, respectively. The several circuits through which the electrically controlled air whistle valve 390 may be operated are controlled by the distance cam contacts operated by the distance cams HWS, LWS and LWS°.

With the car-carried apparatus in its normal condition and with both the high and low cams H and L in their maximum speed position, the warning signal 390 can only be operated by the contacts 174—175 actuated by the sector 142 of the high speed cam H. The circuit for actuating the warning signal 390 completed when these contacts are closed may be traced as follows:—beginning at the bus wire 272, wires 330 and 331, contact 332 of the penalty relay PR, wires 333, 334 and 335, contact 336, wires 337 and 348, contacts 151—152 of the high cam H, wires 338, 370, 392 and 393, contact 394 operated by the low warning signal cam WLS, wire 395, contact 396 operated by the high warning signal cam HWS, wire 397, contacts 174—175, wires 398 and 399, winding of the warning signal 390, wire 400 to the common return wire 273. It is thus noted that with both the cams H and L in their normal restored position that the

warning signal 390 is actuated only if the contacts 174-175 of the high cam H are closed, by reason of the circuit just traced.

Let us assume now that traffic conditions 5 have changed from clear to caution, and that the high cam H is being driven from the wheels of the vehicle and is being moved toward its ultimate position. During this 10 movement of the high cam H, the high warning signal cam HWS is also operated and breaks the warning signal circuit by opening contacts 396. By looking at Fig. 15, it is noted that the contacts 396 operated by the high warning signal cam HWS are 15 again closed when in its normal position and also when in its ultimate position, but that these contacts are open while this cam is being operated from its normal to its ultimate position. In other words, the warning 20 signal circuit just traced will serve to give a warning signal when the high cam H is either in its normal or its ultimate position, but will not permit an alarm to be given while this cam is being changed from its 25 normal to its ultimate position, or vice versa.

Proceeding now on the assumption that the high cam H has already been driven to its ultimate position, let us assume further that the reverse relay R is also deenergized 30 because a change of traffic conditions has taken place, thus initiating the low speed cam upon its cycle of operation. By looking at Fig. 15, it will be noted that a very short time after the low cam L has been 35 initiated the contact 394 controlled by the low warning signal cam LWS is opened, thereby opening the warning signal circuit just traced and preventing an alarm from being given while the low cam is being 40 driven from the wheels of the vehicle to its ultimate position. Just before the ultimate position of the low cam L is reached, the low warning signal cam LWS° will close a contact to complete another warning signal 45 circuit which comprises the same warning signal circuit as heretofore traced up to and including the wire 392 from whence it comprises wire 402, contacts 403 operated by the low warning signal cam LWS°, wire 50 404, contacts 174¹-175¹ operated by the sector 142¹ of the low speed distance cam L, wires 405 and 399, warning signal 390, wire 400 to the common return wire 273.

Circuit arrangements and translating devices have thus been provided for operating the warning signal 390 when the speed limit at either the high, the medium or minimum continuing speed restriction is just about to be exceeded, but is not operated when gradually decreasing speed limits are being enforced, this warning signal in each instance being operated early enough so that the engineer may bring the train under control before an automatic brake application is effected, if he takes immediate action to do so.

It should be noted that the warning signal circuits heretofore traced include the speed-distance automatic brake applying contacts 151-152, 151¹-152¹ of both the high and low speed distance cams. This arrangement is desirable because it stops the warning signal as soon as an automatic brake application has been effected, so as not to cause an audible and possibly disagreeable noise to continue longer than is necessary. 70 75

Penalty for failure to acknowledge.—It has been pointed out hereinbefore that upon proper acknowledgment of a caution signal, the high acknowledging relay H-Ack can be picked up and maintained up through its stick circuit, and that proper acknowledgment of a danger signal causes the low acknowledging relay L-Ack to be picked up and stuck up through its stick contact. The 80 85 penalty resulting when a proper acknowledgment of a change from clear to caution, or caution to danger is not made, will now be considered.

Referring to the penalty relay group 90 shown in Fig. 15 of the drawings, it is noted that the penalty relay PR is energized by a stick circuit, including its stick contact 311, as heretofore traced and having two groups of three multiple contacts in series. 95 One of these groups comprises contacts 361, 308 and 307, and the other comprises contacts 303, 304 and 364. It is also readily apparent that contact 307 is broken immediately and that contact 308 is broken shortly thereafter whenever the normal relay N is deenergized, and that the contact 361 connected in multiple therewith will be broken if a proper acknowledgment is not made when a clear to caution change takes place. 100 This, of course, will deenergize the penalty relay PR permanently. The contacts 303, 304 and 364 function substantially in the same manner as contacts 307, 308 and 361, only that these first mentioned contacts function when a caution to danger change take place; in other words, the contacts of each of these groups (each consisting of three contacts) are connected in multiple and these two groups are connected in series. 105 110 115

Assuming now that the proper acknowledgment has not been made and that the penalty relay PR is deenergized, the engineer will not only be required to limit his speed to fifteen miles per hour until traffic 120 conditions clear up, but will be required to stay at this low speed until he has been penalized in some way, which in the particular arrangement shown consists in enforcing a reduction in speed down to two 125 miles per hour or substantially to a stop. If the engineer exceeds this fifteen mile per hour speed limit as enforced by the fifteen mile per hour cam 365, the E. P. V. will be deenergized and will be maintained in this 130

position until the speed of the train is brought below fifteen miles per hour to allow the contacts 366 to close. By reducing the speed to this value, the pressing of push button PB energizes the relay PBR and picks up the front contact 367 to complete a pick-up circuit for the valve E. P. V. which comprises the circuit through the E. P. V. heretofore traced with the stick contact 340 of the E. P. V. shunted by the wires 370 and 371, front contact 367 of the push button relay PBR, and the wire 372. The momentary closure of this pick-up circuit energizes the E. P. V. which will be maintained energized through its stick contact 338 until the permissive speed limit of fifteen miles per hour is again exceeded. As soon as the speed limit of fifteen miles per hour is, however, again exceeded the brake applying device E. P. V. is again deenergized, requiring the same cycle of procedure to be gone through in order to again energize this E. P. V. Before the train can assume a higher speed limit than fifteen miles per hour, the speed must be reduced to two miles per hour, or to a substantial stop, whereupon the two-mile per hour speed cams 2 m. p. h. shown in the acknowledging relay group are closed, thus closing contacts 406 and 407, respectively.

The closure of the contact 406 completes a pick-up circuit for the low acknowledging relay L-Ack provided the push button PB is operated, which may be traced as follows:—beginning at bus wire 272, wires 352, 376, and 408, contact 406, wires 409 and 380, contact 375 held up by the push button relay PBR, wires 381 and 382, winding of the acknowledging relay L-Ack, wires 383 and 360 to the common return wire 273, thereby causing the stick circuit for the acknowledging relay L-Ack to be completed, providing that the reverse relay R is still in its deenergized position.

Similarly, the contact 407 completes a pick-up circuit for the acknowledging relay H-Ack, which may be traced as follows:—beginning at the bus wire 272, wires 352, 353, and 410, contact 407, wires 411 and 412, contact 350, wires 413 and 358, winding of the acknowledging relay H-Ack, wires 359 and 360 to the common return wire 273. The completion of this circuit energizes the acknowledging relay H-Ack, thus closing its stick contact 356 which is maintained closed providing the normal relay N is still in its deenergized position.

With the acknowledging relays H-Ack and L-Ack energized or their corresponding relays N or R respectively energized, the necessary contacts in the penalty group shown will be closed to complete a circuit for the penalty relay PR as is obvious by looking at the drawings. These necessary

contacts just referred to comprise any one of the contacts 303, 304 and 364 and any one of the contacts 307, 308 and 361. Since, however, the penalty relay PR was deenergized, its stick contact 311 is obviously open, so that these contacts alone can not pick up this relay. Since, however, the speed of the vehicle has been reduced to two miles per hour, thereby closing the contact 414 governed by the cam 2 m. p. h. of the penalty relay group, a pick-up circuit for the penalty relay PR is completed which may be traced as follows:—beginning at the bus wire 272, wires 301 and 416, contact 414, wires 417 and 313, winding of the penalty relay PR, wire 314 to the common return wire 273. With this pick-up circuit momentarily completed, and with either the acknowledging relays or their corresponding relays N and R energized, one of the stick circuits for the penalty relay PR heretofore traced is again completed. It is thus seen that by inflicting a penalty upon the engineer consisting of the requirement to reduce his speed to two miles per hour, he is permitted to pick up the penalty relay PR under either clear, caution or danger traffic conditions. In this connection, it should be noted that the restoring operation of the penalty relay under caution or danger traffic conditions requires a momentary operation of the acknowledging push button PB, whereas this button PB need not be operated to restore the relay PR under clear traffic conditions.

Summary of operation—block signal territory.—Summarizing the various steps in the operation hereinbefore explained under the several headings, it will be recognized that the system of speed control provided by this invention is extremely flexible and affords a high degree of safety with the minimum sacrifice of track capacity.

Vigilance of the engineer and watching out for the indications of the trackway block signals is maintained by compelling him to acknowledge every caution signal indication, under penalty of being obliged to stop the train before he can proceed and exceed the minimum speed of 15 miles per hour. Similarly, the engineer is required to acknowledge each danger or stop signal indication by taking the appropriate action at the point B, it being understood in this connection that regardless of whether or not the signal can be seen from the point B a suitable marker, as shown in Fig. 14, is preferably placed along the track to indicate to the engineer where his acknowledging act must take place. This marker may have a fixed indication or may be controlled from the track circuit of the block ahead, and if it is a controlled signal it is preferably provided with changeable indications, to tell whether or not the signal just ahead indicates stop. It is con-

sidered to be sufficient, however, to provide a simple sign or marker of fixed indication for the point B, since the indications of the cab signals, being at all times under the control 5 of the signal next in advance and automatically changing with any change in the indication of that signal, are adequate to tell the engineer whether or not said signal next ahead indicates danger at the time the train 10 reaches the point B.

While the train is traveling through a caution block, its speed must be kept below certain permissive speed curves prescribed by the cams. If these speed limits for the various 15 points in the block are at any time exceeded, the brakes are automatically applied and kept applied until the train has again come below these speed limits, whereupon the engineer by operation of his push button 20 PB may reset the brake controlling valve EVP and release the brakes.

If traffic conditions ahead clear up at any time and while the train is at any point in a caution block, the speed restrictions are automatically removed and the engineer is advised of this fact by a change of the cab signals or indicators. Consequently, the train may resume speed at the earliest possible 25 moment, with the result that there is no unnecessary delay to trains traveling through congested territory under close headway.

While the train is traveling through a danger block, that is, one guarded by a stop signal, the speed of the train must be kept below a predetermined minimum speed, in order to avoid an automatic brake application. If at any instant this danger block should become unoccupied, or the danger 30 conditions therein, such as an open switch, be removed, the car apparatus on the following train is at once restored and the train is able to proceed at a speed limit appropriate and proper for the changed conditions, that is, caution or clear. The cab signals or indicators advise the engineer of the change in traffic conditions, so that he is able to take advantage immediately of the removal of danger conditions in a danger or 35 occupied block, without waiting to travel throughout the length of this block, expecting to find an obstruction, broken rail, open switch, or other hazard.

Various other specific features and advantages of the system of this invention have 40 been pointed out or will be apparent from the description of the structure and operation.

Unsignalled territory.

From the foregoing explanation of this system, it will, of course, be recognized that a train must receive energy from the trackway in order to proceed at a speed greater 45 than the minimum speed, assumed to be

about 15 miles per hour. In the practical application of this system to railroads, it is obvious that all portions of the trackway used by a locomotive or train can not, as a practical proposition, be supplied with the 70 train control or signaling current. For example, there will be sidings, yard limits, roundhouses, and similar places on a railroad where it would be impractical to supply the simplex and loop circuit currents. Also, it 75 would not be advisable to equip all portions of a railroad or engine division at one time and put the system into service simultaneously over this whole road or engine division. Again, locomotives or trains may be 80 obliged to travel occasionally, particularly in emergencies, over foreign roads. Other conditions may arise in practice where it is desirable to allow the train to travel faster than 15 miles per hour over territory not 85 equipped with signaling current and its control. Consequently, this invention contemplates the provision of means for cutting out the system, or rendering it ineffective to enforce its minimum speed restriction even 90 though the car relay is wholly deenergized because of the failure to pick up simplex or loop circuit current. Obviously, such cut-out or eliminating means, while desirable for 95 unsignalled or unequipped territory, must be safe-guarded in such a way that the engineer can not carelessly or maliciously defeat the objects of the invention and render the system ineffective in regular service in equipped 100 territory.

This desirable control for unsignalled territory is obtained by providing a special relay N S, together with suitable manual and automatic control therefor, such that the desired end may be obtained for unsignalled 105 or unequipped territory, but the safety of the system retained for equipped territory. This relay N S and its control device and circuits is shown in Fig. 15 in the N S relay group. 110

Referring to Fig. 15, the N S relay may be energized by the following circuit:—beginning at the bus wire 272, wires 422 and 423, front contact 424 of the normal relay N, wire 425, front contact 426 of the push button relay P B R, wires 427 and 428, upper winding of the relay N S, and wires 429 and 430 to the other bus 273. 115

It will be noted that this circuit includes the front contact 424 of the normal relay N; and consequently, the relay N S can not be energized under caution or danger conditions. In other words, after speed control is in force in a caution or danger block, the relay NS can not be energized. 120

Entering unsignalled territory.—At the point where the train enters the unsignalled or unequipped territory, it is assumed that the main car relay M R will be energized with a normal clear polarity, and the normal 125 130

relay N will be picked up. If desired, this result may be assured by providing a track section, permanently supplied with loop and simplex circuit currents of normal polarity, 6 at the entrance to each portion of unsig- nalled territory. Such permanently clear section, among other things, might obviate the necessity of the train waiting in the last block of signalled territory until this block 10 became clear.

Assuming the normal relay N to be energized, at the time the train is about to enter the unsignalled territory, this point being indicated by a suitable sign or marker, the 15 engineer is expected to operate the push button P B, picking up the push button relay P B R and energizing the upper winding of the relay N S by the circuit just traced. As the train then enters the unequipped or un- 20 signalled territory, and the main car relay M R is deprived of energizing current, the relays N and R both drop simultaneously, closing their back contacts 282 and 292 at substantially the same instant, thereby es- 25 tablishing a stick or retaining circuit for the lower winding of the relay N S as follows:— commencing at the bus 272, wires 275 and 281, back contact 282 of relay N, wire 291, back contact 292 of relay R, wire 295, front 30 contact 296 of relay N S, wires 431 and 432, lower winding of relay N S, and wires 433 and 430 to the other bus 273.

It will be observed that the energizing circuit for the upper winding of the relay N S is broken at the front contact 424, while the stick circuit for the lower winding is being completed at the back contact 282 of the normal relay N; and the relay N S is preferably made slightly slow acting in 40 dropping to span this slight time interval, or by well known expedients, said front and back contacts are made slightly overlapping in their operation.

The relay N S, when energized, renders 45 the system inactive and performs functions as follows:—

(a) The opening of its back contact 296, 50 interrupts the circuit for the red lamp R, so that, although both the normal and reverse relays N and R are deenergized in the un- 55 signalled territory, the red lamp is not lighted. The green and yellow lamps, are, of course, extinguished by the relays N and R themselves. Thus, there are no cab signals or indicators appearing while the train is traveling in unsignalled territory, thereby avoiding all chance of confusing or misleading the engineer.

(b) With the relay N S energized, there 60 is established a circuit for lighting the lamp W, this circuit being the same as the stick circuit N S previously traced, up to the wire 432, and thence by wire 435, through lamp W, and wires 436, 299, and 289 to the 65 bus 273.

The lamp W represents a suitable indicator or cab signal giving a special or distinctive indication, in this instance assumed to be a white lamp. This special no-signal indication is constantly displayed before the 70 engineer while his train is traveling in un- signalled territory and serves to remind him that the train is running without the protection of the automatic speed control system, the responsibility for the safety of the 75 train being wholly in his hands and re- quiring care and a speed permitting stop- page within vision.

(c) The relay N S, when energized, closes 80 front contacts 437 and 438, which, as will be readily seen from the circuits in Fig. 15, shunts the front contacts 320 and 326 of the normal and reverse relays N and R, and maintains the high cam starter magnet H C S and the low cam starter magnet 85 L C S energized, irrespective of the drop- ping of said relays N and R. In short, the relay N S maintains the cams in their normal or initial speed conditions, in spite of the deenergization of the relays N and R. 90

(d) The front contact 439 of the relay N S maintains a shunt for the low speed cam-distance contacts 151¹—152¹, in spite of the opening of front contact 336 of the reverse relay R, thereby permitting the train 95 to travel at the maximum speed determined by the high speed cam-distance contacts 151—152. It is noted here, that, if it is de- sired to enforce the intermediate or medium speed limit in unsignalled territory, the front contact 439 of the relay N S may be 100 omitted; or, by adaptations of simple character and readily apparent, speed contacts for any desired limit may be inserted in series with a front contact 439 of the relay 105 N S, so that a special speed limit may be provided for unsignalled territory, a speed limit different from the maximum, the medium, or the minimum speed otherwise 110 available.

One peculiarity of the circuit arrange- 115 ment of Fig. 15 meriting consideration is that the relay N S is energized each time the push button P B is operated, while a train is traveling under a clear signal. For example, each time the engineer ac- 120 knowledges a caution signal, the relay N S is energized. This condition, however, is merely temporary or transient. Even though the relay N S is energized, the pick- 125 ing up of the push button relay P B R which is necessary to energize N S opens at its back contact 316 the circuits for the high and low cam starter magnets H C S and L C S thereby bringing about the enforcement of a restricted speed limit. Hence, the engineer derives no advantage by holding down the push button P B with the idea of keeping the relay N S energized. If upon the acknowledgment of a caution 130

signal, as soon as a caution block is entered, and the normal relay N drops, the energizing circuit for the relay N S is broken, its stick circuit is open at the back contact 292 of the reverse relay R, with the result that the relay N S remains deenergized and can not thereafter be energized until a clear signal control is received from the trackway. It will be observed that the temporary energization of the relay N S while a caution signal is being acknowledged, does not change the cab signal indicators R and Y, because the reverse relay R, at least, is energized at this time.

15 As a result of the control of the relay N S just described, this relay can not be energized and maintained energized except when there is a change from clear control to danger control, that is, from the condition where the normal relay N is energized to the condition where both the relays N and R are simultaneously deenergized. Such a change from clear to danger does not occur in the regular operation, each danger 25 change being anticipated by a change from clear to caution, the only exception being where there is a broken rail in the same block, or an open switch, or the like. Consequently, the no-signal territory condition 30 can only be set up where unsignalled territory actually exists, that is, in running from clear to danger, because even in those cases where a broken rail or the like in the same block produces a sudden change from clear 35 to danger, the relay N S will not be energized inasmuch as the engineer, not knowing that such condition will occur, will not have operated his push button P B.

40 *Re-entering signalled territory.*

The relay N S, once its stick circuit is established, will remain energized until the normal relay N or the reverse relay R picks up, or until the car picks up loop and simplex currents of the normal or the reverse polarity. Consequently, as soon as the train 45 re-enters signalled territory, in which loop and simplex circuit currents are supplied, the relay N S is automatically deenergized and the proper speed control for the train is automatically put into effect.

When the relay N S is deenergized, the white lamp W is extinguished, and the green or yellow lamps Gr or Y are lighted; the 50 cam starter magnets H C S and L C S are put back under the control of the main car relay M R; and the opening of the front contact 439 of the relay N S renders the low cam effective to enforce its speed limits, 55 if necessary.

60 *Emergency control for unsignalled territory.*

The setting up of the control for unsignalled territory requires, as above explained, 65 a manual operation on the part of the en-

gineer at the right time. It may happen, however, that the engineer will not make timely operation of the push button P B and his train may get into unsignalled territory without having the relay N S energized. While the train may, of course, even then proceed at some speed lower than the minimum of 15 miles per hour, the stretch of unsignalled territory may be long and a higher speed desirable. Considerable delay and danger to following trains might result if the engineer attempted to back up into signalled territory and try to carry out the proper procedure in entering the unsignalled territory.

Also, there may be occasional power failures, where several blocks of the railroad will be "dead", due to trouble with the transmission line or similar accidents. Such power failure, could not, of course, be anticipated by the engineer and permit him to pick up the relay N S, with the result that without using some other special emergency cut out, the train or trains affected by this power failure could not proceed faster than the minimum speed limit of 15 miles per hour.

To take care of these contingencies, a special push button 440 for energizing the relay N S is provided, together with contacts 441 closed only if the speed of the train is below 2 miles per hour or substantially at a standstill. This emergency push button 440 is in practice located in a sealed or locked box, equipped with a recorder or otherwise safeguarded so that its use can not be abused. If the engineer should fail to take the appropriate action in entering unsignalled territory, or there should be an unexpected power failure, the train may be brought to a stop and the push button 440 operated to pick up the relay N S through a circuit:—commencing at bus 272, wires 422 and 443, 2 mile per hour contact 441, wire 444, push button 440, wires 445 and 428, upper winding of N S relay, and wires 429 and 430 to the other bus 273.

Both of the relays N and R being under the conditions assumed deenergized, a stick circuit for the relay N S is at once established; and the train may proceed under the regular unsignalled territory control.

80 *Against traffic movements.*

In the practical operation of railroads, trains sometimes have to move over a stretch of track, signalled and equipped with train control for train movement in one direction only, in a direction opposite to this normal direction of traffic. Such movements against the normal direction of traffic are rare and are made only under special order; but with the system of this invention, such a movement could not be made at a speed in excess of the minimum speed, unless

special provisions are made, because the train in traveling against the normal direction of traffic would not be picking up the loop circuit current. Such an against traffic movement, may be used to be the same as or the equivalent of a movement through un-signalled or unequipped territory; and it is proposed to use the relay N S and associated devices for facilitating such against traffic movements in the same way as when the train enters and travels through un-signalled territory.

Except in very exceptional and emergency cases a proper and authorized train movement against the normal direction of traffic will originate at an interlocking plant; and when the track is set up for such an against traffic move, provisions are made in a manner which will be obvious to supply to the train both simplex and loop circuit current of normal polarity, that is, to give clear control, just before the train actually begins the against traffic movement and loses the loop circuit current. Conditions, therefore, may be made to correspond to that existing at the entrance to un-signalled territory, so that by operation of the push button P B, the engineer may pick up the relay N S, with the results already explained, and run his train against the normal direction of traffic at more than 15 miles per hour.

As soon as the train takes a crossover or otherwise begins a movement in the normal direction of traffic on an equipped track, the relay N S is automatically deenergized, due to the picking up of either the normal relay N or the reverse relay R. Thus, the train control system is automatically made effective as soon as the train gets back under conditions where such system may be used.

Danger conditions suddenly arising.

One important feature of the system of this invention is the safety afforded in the event of the sudden appearance of a hazardous condition immediately ahead. For example, a rail may break ahead of a train in the same block, or a switch in the same block occupied by the train may be improperly opened, or a draw bridge opened, or other hazardous conditions detectable by the flow of loop circuit current may suddenly and unexpectedly arise. It is, of course, evident that such hazardous conditions may suddenly arise when it is too late to stop, but in this event no system of train control can serve to prevent an accident. With the present system, however, it is assured that the brakes are automatically applied irrespective of the speed instantly whenever a danger condition arises in the same block occupied by the train, with the result that automatic stoppage of the train is brought about at the earliest possible moment.

A broken rail or other hazardous condition suddenly arising interrupts either or both the simplex and loop circuit currents and immediately causes deenergization of the main car relay M R and both of the relays N and R. As previously explained, the dropping of either of the relays N or R, unless anticipated by an appropriate acknowledging act on the part of the engineer results in the deenergization of the penalty relay P R, thereby at once deenergizing the electro-pneumatic valve E P V, and producing an automatic brake application. Since the engineer has no way of knowing when this broken rail or other hazardous condition will suddenly arise, the acknowledgement will obviously not be made; and consequently, such sudden change to danger results in an automatic brake application. After deenergization, the penalty relay P R has to be restored in the same way as already explained.

Adjustments for passenger and freight service.

On some railroads, certain locomotives are at times used in passenger service and at other times for freight service. There is, however, a considerable difference in the braking power of passenger and freight trains; and for reasons well recognized in the art, it is expedient to employ different speed limits for freight and passenger service. In those cases just noted where the same locomotive is used for both classes of service, it becomes necessary to provide extra or double speed control equipment, one set or group of devices being adaptable for passenger service and the other for freight service. With such dual equipment, it is further necessary to provide a safe way of determining whether the freight or the passenger speed limits shall be effective.

While various expedients may be employed for permitting the adjustment or selection of the equipment of a locomotive to put it in condition for pulling a freight train or passenger train as the case may be, in the present invention it is proposed to provide a manually operable changeover device or switch which will alternately cut in the passenger and freight equipment, this changeover device being enclosed in a locked box or casing, the key to which is held by a suitable authorized person such as the yard foreman, so that the changeover for freight and passenger service can only be made properly. The need for safeguarding this changeover device follows from the fact that the speed limits for a passenger train are higher than those for a freight train, and if it were possible for the engineer at any time to make the change, he might be tempted, while pulling a freight train, to change over to the passenger train speed limits,

is desirable to place suitable signs or markers, especially where the point of speed reduction can not be easily remembered or recognized by the engineer, so that the engineer may be warned and may acknowledge in the regular fashion, hereinafter explained, and avoid deenergization of the penalty relay P.R.

10 *Blocks of different lengths.*

The track-way apparatus, as shown in Fig. 14, includes a block J which is substantially of such length that if the high cam H is initiated upon entering this block J and the low cam L is initiated substantially at that point in the block where the high cam reaches its ultimate position, this low cam will reach its ultimate position when the train reaches the end of the block. In other words, the block J is a block of substantially ideal length for the particular speed limits selected for a particular system.

In considering this problem of adapting the system to different length blocks, it should be appreciated that the run out distances of the H and L cams are fixed distances. It should also be understood that the train must conform to the lowest speed limit being enforced, so that if a low cam is acting, the speed limit is that prescribed by the position of that cam, consequently, with the organization of the system as described, there is a certain distance of travel or block length required to run the high cam from its initial maximum speed position to its lower or medium speed position, and then run down the low cam from its initial or medium speed position to its ultimate or minimum speed position. A block longer than this distance interval, therefore, means, assuming the high cam to be started at the beginning of the block, a certain distance of travel of the train at the medium speed limit after the high cam has run out, and before the low cam is started. In the case of very long blocks, the reduction in speed at the beginning of the block, occasioned by running down the high cam, may occasion unnecessary delay, inasmuch as the same reduction in speed may be made safely at a later time during the run and at a more advanced position of the train in the block.

Conversely, blocks shorter than the fixed spaced interval required to run down both of the cams, will not safely permit of the same treatment as the conventional length block illustrated in Fig. 14, since it is too late to start the high cam at the entrance to this short block. One remedy for the shorter blocks which is thought will be evident from the consideration of the foregoing discussion, is to use the low cam only for control throughout these short blocks, that is, have the caution control permanently effective and corresponding to the absence of other trains

and imposing the danger control at the entrance to each of these short blocks under caution conditions, situations may arise, however, where the desired block length will be longer than the run out distance of the low cam but still less than the run out distance of both cams; and such a situation requires a special arrangement of trackway circuits.

70

10 *Modification of car circuits.*

The car circuits and equipment as shown in Fig. 15 comprise devices for requiring the engineer to acknowledge each change from clear to caution and from caution to danger, under penalty of being stopped in order to proceed more than 15 miles per hour. As already explained, this acknowledging feature is considered preferable in order to stimulate vigilance on the part of the engineer and insure the observance of the trackway signals of the block signal system. It is reasoned that this acknowledging arrangement makes it an object for the engineer to watch out for the indications of the block signals; and having attained this result, it is the theory that the safety for the train provided by the automatic speed control system, will be additionally assured by the vigilance and care of the engineer.

95

The same general theory of vigilance may be carried out on a different line by assuming that, if the engineer reduces speed and maintains the proper speed limits, without the guidance of any warning signal, it is assured that the engineer has observed the trackway signals and is acting upon their indications. According to this theory of maintaining vigilance, it is not necessary to provide acknowledging devices or a penalty for failure to acknowledge but on the contrary provide a penalty in case the speed limits are at any time exceeded.

100

A modified arrangement of the car circuits bringing out, among other things, this different arrangement for maintaining vigilance, is shown in Fig. 17. Many of the parts and circuits illustrated in Fig. 17 are the same as shown in Fig. 15 and already fully explained. The control relay and indication group, the NS relay group and the cam starter group are identical with what is shown in Fig. 15, and these circuits require no further discussion. The acknowledging relay group and penalty relay group of Fig. 15 are omitted in Fig. 17. Fig. 17 shows provisions for adjusting the equipment for freight and passenger service analogous to but somewhat different from that shown in Fig. 16. In this modified arrangement of Fig. 17, the changeover switch COS is a single pole switch and controls the energization of a changeover relay CO, it being contemplated that this changeover relay will be located in the casing for the

115

120

125

130

and thereby eliminate any interference of his train by the speed control apparatus.

Referring to Fig. 16, there is illustrated in a simplified and diagrammatic manner 5 part of the devices and circuits of the car equipment as it would be changed from what is shown in Fig. 15 for locomotives intended to be used sometimes in freight service, and sometimes in passenger service. Since the 10 change in equipment needed to adapt it for freight and passenger service refers only to the speed limits, Fig. 16 illustrates only the parts and circuits involved in determining the speed limits at which the warning 15 signal and the automatic brake application will occur.

Fig. 16 shows two groups or sets of cams, one for passenger service, and the other for freight service, each group or set comprising 20 the high to medium and the medium to low cams, four cams altogether. The high and low cams intended for passenger service have been designated H^p and L^p ; and the corresponding cams for freight service have been 25 designated H^f and L^f . It will be noted that these cams for freight and passenger service have been shown as having a slightly different shape to indicate that the maximum, 30 medium, and perhaps the minimum speed limits may be different for the two classes of trains. The cam shapes shown, are, of course, merely illustrative. Generally speaking, the changeover device or switch C O S (shown diagrammatically as a plunger 447 35 and switch blades enclosed in a locked box indicated by the dotted rectangle 448) is used to connect the circuits of the freight and passenger cams alternately into the external circuits associated therewith. As 40 shown in Fig. 16, the changeover switch C O S is in position to give the passenger train set-up. The circuits and connections resulting correspond in all particulars to those already explained in connection with Fig. 45 15. and for convenience are given the same reference characters with distinctive exponents "p". When the changeover switch C O S is shifted, an analogous and corresponding 50 circuit arrangement is established for the freight cams; and the new wires involved in this freight set-up are given the same reference numbers with the distinctive exponents "f". With this explanation of the need of Fig. 16, and in view of the full description of Fig. 15, it is thought to be unnecessary to point out in detail the various 55 circuits involved for the brake setting device E P V and the warning signal, for the freight and the passenger set ups, these circuits being readily traced on Fig. 16 from analogy to those on Fig. 15.

Speed control for permanent hazards.

There are frequently encountered places 60 on railroads where a restricted speed limit

should be observed at all times, irrespective of the presence of other trains. For example, a sharp curve may necessitate restricted entrance speed, or yard limits may demand a speed reduction. These and other well-known so-called permanent hazards require 70 a speed limit different from the high, the medium, or the minimum afforded by the high and low cams, or some one of these speeds may be suitable. To illustrate, some 75 crossover or curves may be safely taken at the medium speed, assumed to be about 40 miles per hour, while other crossovers or turnouts should be taken at a lower speed, not necessarily as low as the 15 mile per 80 hour minimum speed.

Bearing in mind these variable conditions encountered in practice, any one of the three different speed limits provided by the cams may be put into effect at any place along the 85 track independent of traffic conditions, by reorganizing the simplex and loop circuits accordingly so as to impose, under clear traffic conditions, the desired speed restriction, these speed limits for the permanent hazards 90 being, of course, reduced if necessary when traffic conditions require.

In those cases where the three speed limits available by changing the polarity or phase 95 relation of the simplex and loop circuit currents or by cutting off one of these currents are sufficient; other intermediate speed limits may be obtained by initiating the operation of either the high or low cam, running that cam down to the point where the desired intermediate speed limit exists, and then automatically restoring that cam back to its initial or normal condition. The way in which the trackway control circuits are adapted to bring about this operation will be 100 apparent and need not be specifically illustrated. With the cams operated in this fashion, it will be evident that the train will be obliged to reduce speed to the desired intermediate speed in order to avoid an automatic brake application. Of course, when 105 the cam is restored, the speed limit is raised and the train may accelerate; but this arrangement can be used to "pinch down", so to speak, the normal running speed limit under clear traffic conditions, to suit the curves, 110 crossovers, or permanent hazards of similar character. Where an intermediate speed limit should be enforced for a considerable distance of travel, this same operation of "pinching down" may be repeated at intervals close enough together to prevent acceleration of the train between the control points to a dangerously excessive speed, with 115 the practical result of enforcing a substantially uniform intermediate maximum limiting speed.

In connection with these points of permanent hazards, where a permanent caution or danger control is automatically imposed, it 120

speed control apparatus and the changeover switch at some suitable and accessible point on the locomotive.

Referring to the EPV group of Fig. 17, 5 two sets of cams for freight and passenger service are shown; and since these cams and associated circuits are the same, a description of one will suffice for both. Assuming the set-up for the passenger service, as 10 shown, a brake control device EPV is energized by a circuit as follows, assuming normal clear running conditions:—commencing at the bus 272, wires 470, 471 and 472, contacts 473 of the distance unit L^d on 15 the low cam shaft, wires 474 and 475, contacts 151—152 of the high cam, wire 476, contact 477 of the changeover relay, wires 478 and 479, front contact 340 of the device EPV, wires 480 and 481, EPV winding, and 20 wire 482 to the other bus 273.

The distance unit L^d on the low cam shaft, as illustrated, is closed with this cam shaft in the normal position but opens after a short distance of travel as soon as said cam shaft 25 is geared to the wheels by the deenergization of the low cam starter magnet LCS. The contacts 473 of this distance unit L^d together with wires 472, 474, 483 and 484 form a shunt for the contacts 151—152¹ of the low 30 passenger cam. Consequently, under normal clear running conditions, with the low cam starter magnet LCS energized and the contacts 473 closed, the contacts of the high cam are controlling; but upon deenergization 35 of said low cam starter magnet, the opening of contacts 473 renders the contacts of the low cam effective to control, so that the speed must be below the speed limits prescribed by the low cam in order to avoid a brake 40 application.

It will be noted that the normal energizing circuit for the brake control device EPV includes its own front contact 340, these contacts being instantly opened upon deenergization of this device. Consequently, when 45 an automatic brake application occurs, this application persists or continues until the device EPV is reset. This resetting is accomplished by shunting the contacts 340, so that the device EPV may be energized by 50 the resetting circuit. This shunt comprises wires 485, two miles per hour contacts 486, wire 487, front contact 367 of the push button relay PBR, and wire 488. Hence, before 55 the device EPV can be restored, not only must the speed have been reduced and the cam contacts closed, but also the train must be brought down to 2 miles per hour, or substantially to a standstill, and the push button PB operated. The re-energization of the 60 valve EPV might perhaps result in a release of the automatic brake application, assuming the engineer's brake valve to remain in the normal running position, and depending upon 65 the character of the brake control mecha-

nism employed, but such automatic release is rendered impossible by the use of the contact 367 of the push button relay. In short, the engineer must take positive action after an automatic application to release the brakes. 70 For various reasons, familiar to those skilled in the operation of the ordinary air-brake system, it is desirable to do this and avoid any automatic release of the brakes after an automatic brake application. 75

Since the train must be brought down to 2 miles per hour or substantially to a stop in order to proceed after each automatic operation of the brake control device EPV, it becomes an object for the engineer to 80 avoid such automatic operation by maintaining his speed below the limits prescribed by the system. In other words, the vigilance of the engineer is stimulated by penalizing him for every automatic brake application, with 85 the result, it is thought, that the engineer will keep alert, be watchful of the indications of the trackway signals, and will control his speed safely. In this connection, it should be understood that a suitable reset, 90 accessible only from the ground and safeguarded against use, can be employed for restoring the device EPV, in lieu of the two miles per hour contacts.

It is contemplated that audible signals, together with control circuits therefor, as shown shown in Fig. 15, are preferably used with the wiring arrangement shown in Fig. 17, this warning signal being normally on open circuit but operated upon closure of that circuit, as shown in Fig. 15, or, normally on 100 closed circuit and operated by the opening of that circuit.

Having thus shown and described several specific systems embodying the present invention, it is desired to be understood that certain specific disclosures have been made for the purpose of illustrating the nature of the invention, rather than the scope thereof, and that the invention is not limited to the 105 specific structure illustrated. Also, the invention does not alone reside in the particular systems disclosed, but also resides in certain sub-combinations and elements; and it is to be understood that various changes 110 and modifications may be made to adapt the invention to the various types of railway 115 systems in connection with which it is to be used.

What is desired to be secured by Letters 120 Patent of the United States, is:—

1. Car-carried apparatus for automatic train control systems of the type in which control influences are inductively transmitted from the trackway to suitable receiving apparatus on the vehicle comprising, an electro-responsive device for indicating clear, caution and danger, respectively, a normally energized penalty relay energized by a circuit including its front contact, and 125

means for interrupting said circuit in response to the condition of said electro-responsive device unless a manually operable device is operated during and prior to the time a clear to danger change of traffic conditions is manifested by the car-carried equipment.

2. Car-carried apparatus for automatic train control systems of the type in which control influences are inductively transmitted from the trackway to suitable receiving apparatus on the vehicle comprising, an electro-responsive device for indicating clear, caution and danger, respectively, a normally energized penalty relay energized by a circuit including its front contact, and means controlled by said electro-responsive device for interrupting said circuit unless a manually operable device is operated during and prior to the time a caution to danger change of traffic conditions takes place.

3. Car-carried apparatus for automatic train control systems of the type in which control influences are inductively transmitted from the trackway to suitable receiving apparatus on the vehicle comprising, an electro-responsive device for indicating clear, caution and danger, respectively, a normally energized penalty relay energized by a circuit including its front contact, and means for breaking said circuit unless a manually operable acknowledging device is operated at the time a clear to caution change of traffic conditions takes place.

4. Car-carried apparatus for automatic train control systems of the type in which control influences are inductively transmitted from the trackway to suitable receiving apparatus on the vehicle comprising, an electro-responsive device for indicating clear, caution and danger, respectively, a normally energized penalty relay energized by a stick circuit, and means for temporarily interrupting said stick circuit when traffic conditions change from a favorable to an unfavorable condition, and manually operable means effective when operated to prevent the momentary interruption of said circuit.

5. Car-carried apparatus for automatic train control systems of the type in which control influences are inductively transmitted from the trackway to suitable receiving apparatus on the vehicle comprising, an electro-responsive device for indicating clear, caution and danger, respectively, a non-signal territory relay having a pick-up circuit and a stick circuit including a front contact of said relay, manually operable means for closing said pick-up circuit under clear traffic conditions only, and means automatically operated for closing said stick circuit at another point in series with said front contact under danger traffic conditions, whereby if a clear to danger change of traffic conditions takes place while said manually

operable means is operated said relay will be maintained energized through its stick circuit.

6. Car-carried apparatus for automatic train control systems of the type in which control influences are inductively transmitted from the trackway to suitable receiving apparatus on the vehicle comprising, an electro-responsive device for indicating clear, caution and danger, respectively, a non-signal territory relay having a pick-up circuit and a stick circuit including a front contact of said relay, manually operable means for closing said pick-up circuit under clear traffic conditions only, means automatically operated for closing said stick circuit at another point in series with said front contact under danger traffic conditions, whereby if a clear to danger change of traffic conditions takes place while said manually operable means is operated said relay will be maintained energized through its stick circuit, and means to penalize the engineer if said manually operable means is operated longer than a predetermined period of time.

7. Car-carried apparatus for automatic train control systems of the type in which control influences are continuously transmitted inductively from the trackway to suitable receiving apparatus on the vehicle in response to currents flowing in two trackway circuits including the track rails comprising, an electro-responsive device for indicating clear, caution and danger, respectively, depending on the presence and phase relation of these currents, a permissive speed device changed in accordance with the progress of the vehicle, an actual speed device, an electro-pneumatic brake applying means for controlling the usual air brakes of a railway train, a circuit for energizing said electro-pneumatic brake applying means controlled jointly by said permissive speed device and said actual speed device, whereby if the actual speed exceeds the permissive speed the brake applying means is de-energized and causes an automatic application of the brakes.

8. Car-carried apparatus for automatic train control systems of the type in which control influences are inductively transmitted from the trackway to suitable receiving apparatus on the vehicle comprising, an electro-responsive device for indicating clear, caution and danger, respectively, an electro-pneumatic brake applying means for controlling the usual air brakes of a railway vehicle, a circuit for energizing said brake applying means including two contacts in series, means for controlling the first of said contacts including a permissive speed device adapted to set up various speed limits between a maximum and a medium speed limit which will open said contact if the actual speed of the vehicle exceeds the permissive

- speed set up, means for controlling the second of said contacts including a permissive speed device adapted to set up various speed limits between said medium speed limit and a lower speed limit which will open 5 said second contact if the actual speed exceeds the permissive speed set up by this device, and means for shunting said second contact under predetermined traffic conditions ahead. 10
9. Car-carried apparatus for automatic train control systems of the type in which control influences are inductively transmitted from the trackway to suitable receiving apparatus on the vehicle comprising, an electro-responsive device for indicating clear, caution and danger, respectively, an electro-pneumatic brake applying means for controlling the usual air brakes of a railway 15 vehicle, a circuit for energizing said brake applying means including two contacts in series, means for controlling the first of said contacts including a permissive speed device adapted to set up various speed limits between a maximum and a medium speed limit which will open said contact if the actual speed of the vehicle exceeds the permissive speed set up, and means for controlling the second of said contacts including a permissive speed device adapted to set up various speed limits between said medium speed limit and a lower speed limit which will open said second contact if the actual speed exceeds the permissive speed set up by this 30 device. 35
10. Car-carried apparatus for automatic train control systems of the type in which control influences are inductively transmitted from the trackway to suitable receiving apparatus on the vehicle comprising; an electro-responsive device for indicating clear, caution and danger, respectively; a normally energized penalty relay energized by a stick circuit; means for interrupting said stick 40 circuit when the vehicle has traveled a predetermined distance in territory where adverse traffic conditions exist; and manually operable means effective if operated before said vehicle enters the territory where adverse traffic conditions exist for independently closing the stick circuit of said penalty relay. 45
11. Car-carried apparatus for train control systems of the type in which a continuous control influence of a particular character must be transmitted from the trackway to the vehicle in order to permit the vehicle to proceed restricted only to a maximum speed limit comprising, electro-responsive means adapted to indicate clear, caution and danger respectively, a manually operable acknowledging device, means for penalizing the engineer if he does not actuate the manually operable device while a clear to caution, 55 a caution to danger or a clear to danger 60
- change of said electro-responsive device takes place, and means for restricting the progress of the train if said manually operable acknowledging device is left in its active position permanently. 65
12. An automatic train control system comprising, electro-responsive means on a vehicle for indicating clear, caution and danger, respectively, a normally energized penalty relay, means for deenergizing said penalty relay when a clear to caution or a caution to danger change of said electro-responsive device takes place, a normally deenergized non-signalled territory relay, and manually operable means which if operated while a clear to caution or a caution to danger change of the electro-responsive means takes place will prevent said penalty relay from being deenergized and if operated while a clear to danger change takes place 70 will prevent the penalty relay from being deenergized and will pick up said non-signalled territory relay. 75
13. Car-carried apparatus for automatic train control systems comprising, an electro-responsive means for indicating clear, caution and danger, respectively, in accordance with control influences transmitted from the trackway, a penalty relay energized by a stick circuit including a contact closed when 80 said electro-responsive means is in its clear condition, an acknowledging relay having a pick-up circuit and a stick circuit including its front contact and having a front contact in multiple with said first mentioned contact, and manually operable means effective only when said electro-responsive means is in its clear traffic condition for completing the pick-up circuit of said acknowledging relay, and means for closing the stick circuit of said acknowledging relay at another point when said electro-responsive means is in the caution traffic condition. 85
14. Car-carried apparatus for automatic train control systems comprising, an electro-responsive means for indicating clear, caution and danger, respectively, in accordance with the presence and character of control influences transmitted to the vehicle, a normally energized penalty relay adapted to be deenergized when a clear to caution change of traffic conditions takes place, an acknowledging relay for maintaining said penalty relay energized independently of its control by said electro-responsive means and having 90 a pick-up and a stick circuit, means for supplying current to said pick-up and said stick circuits in overlapped relation including a make-before-break switch, and manually operable means for closing said pick-up circuit at another point, whereby if said manually operable means is operated when a clear to caution change takes place said acknowledging relay is picked up and maintains said penalty relay energized. 95

15. An automatic train control system including car-carried apparatus comprising, an electro-responsive means for indicating clear, caution and danger, respectively, in accordance with the presence and character of control influences transmitted to the vehicle, a normally energized penalty relay adapted to be deenergized when a clear to caution change of traffic conditions takes place, an acknowledging relay for maintaining said penalty relay energized independently of its control by said electro-responsive means and having a pick-up and a stick circuit, means for supplying current to said pick-up and said stick circuits in overlapped relation including a make-before-break switch, manually operable means for closing said pick-up circuit at another point whereby if said manually operable means is operated when a clear to caution change takes place said acknowledging relay is picked up and maintains said penalty relay energized, and means for penalizing the engineer if said manually operable means is operated longer than a predetermined period of time.

16. Car-carried apparatus for automatic train control systems comprising, a permissive speed device controlled in accordance with control influences transmitted from the trackway, said device prescribing a constant high speed limit when in its normal condition, a gradually decreasing speed limit when in its initiated condition and a constant lower permissive speed limit when in its ultimate condition, an actual speed device, an alarm, means for sounding said alarm when said actual speed approaches the permissive speed within a certain limit, and automatic means for making said last mentioned means ineffective while said device is changing from its normal to its ultimate position.

17. Car-carried apparatus for automatic train control systems comprising, an electro-responsive means for indicating clear, caution or danger in accordance with the control influences transmitted at a particular time, a manually operable acknowledging device, means for penalizing the engineer if said acknowledging device is not operated prior to and during the time an unfavorable change of traffic conditions takes place in accordance with the indications of said electro-responsive means, a cam adapted to be driven by the axle of the vehicle and coupled to said axle when said responsive means is in either the caution or danger traffic condition, and means for coupling said cam to said axle while said manually operable means is operated.

18. Car-carried apparatus for automatic train control systems comprising, a three-position polarized control relay controlled in accordance with control influences trans-

mitted from the trackway, two repeater relays, means for controlling said repeater relays by said control relay including means for energizing one of said repeater relays by said control relay only when said control relay is energized to the normal position, energizing the other repeater directly by said control relay only when said control relay is in its reverse position, and means for energizing said other repeater relay by said first mentioned repeater relay when this first mentioned repeater relay is in its energized position.

19. Car-carried apparatus for automatic train control systems comprising, an electro-responsive device for indicating clear, caution and danger in accordance with control influences transmitted, a permissive speed device, an actual speed device, a normally energized brake control device energized by a stick circuit including its front contact, means for interrupting the stick circuit for said brake control device when the actual speed of the vehicle exceeds the permissive speed, and manually operable means for shunting the front contact of said brake control device whereby the brakes may be released by the engineer providing the speed of the vehicle is below the speed limit set up by said permissive speed device.

20. Car-carried apparatus for automatic train control systems comprising, a normally energized penalty relay, means effective if said penalty relay is deenergized for setting up a low permissive speed limit which if exceeded will cause an automatic brake application, a manually operable device, and means effective if the speed is reduced to a predetermined and still lower value for again energizing said penalty relay providing said manually operable means is operated at the same time.

21. In an automatic train control system, the combination of a normally energized car-carried relay energized in response to current flowing along the trackway, a delayed action device delayed in accordance with the progress of the vehicle along the trackway and governed by said relay, means governed by said delayed action device and effective to cause an automatic application of the brakes a predetermined distance of travel after such relay has been changed to a position indicating adverse traffic conditions ahead, and manually operable means for preventing an automatic application of the brakes by said last mentioned means effective if operated prior to such adverse change in traffic conditions ahead.

22. In an automatic train control system, the combination of a normally energized car-carried relay energized in response to current flowing along the trackway, a delayed action device delayed in accordance with the

progress of the vehicle along the trackway and governed by said relay, means governed by said delayed action device and effective to cause an automatic application of the 5 brakes a predetermined distance of travel after such relay has been changed to a position indicating adverse traffic conditions ahead, and manually operable means which if operated before said relay is de-energized 10 prevents an automatic brake application by said last mentioned means.

23. Car-carried apparatus for automatic train control systems comprising, a normally energized penalty relay energized by a circuit 15 including a front contact of said relay, means actuated from the trackway for opening said circuit at a certain point when a section is entered in which traffic conditions are more dangerous, and manually controllable 20 means for completing a shunt around said point, said manually controllable means being effective only if it is initiated before the more dangerous traffic section is entered.

24. Car-carried apparatus for automatic 25 train control systems of the continuous inductive type comprising, a control relay normally maintained energized by currents flowing along the trackway, an automatic brake setting device, means for actuating said device 30 vice if the train has traveled a predetermined distance while said relay has assumed an abnormal position, and manually operable means which if momentarily actuated at a point less than a certain distance in the rear 35 of the point at which said predetermined distance terminates prevents said automatic brake setting device from being actuated by said last mentioned means.

25. Car-carried apparatus for automatic 40 train control systems of the continuous inductive type comprising, a control relay normally maintained energized by currents flowing along the trackway, an automatic brake setting device, means for actuating said device 45 vice if the train has traveled a predetermined distance while said relay has assumed an abnormal position, and a manually operable stick device which if placed in its active condition under certain conditions remains 50 in such condition until said predetermined distance has been traversed and which prevents actuation of said brake setting device by said last mentioned means.

26. In a car-carried apparatus for automatic 55 train control systems, the combination of a relay which responds immediately to a change of traffic conditions ahead regardless of the position of the train in a block, an acknowledging device, a distance 60 element governed by said relay and changed in accordance with the progress of the train along the track, and means actuated by said distance element effective to apply the brakes of the train if the train has traveled for more 65 than a predetermined distance since the de-

energization of said relay unless the engineer has manifested his vigilance by operating said acknowledging device.

27. In a car-carried apparatus for automatic train control systems, the combination 70 of an electro-responsive means which is adapted to indicate clear, caution and danger in response to traffic conditions ahead of the car and which is energized under clear traffic conditions ahead by current flowing in a 75 trackway circuit, an acknowledging device, a distance mechanism governed by said electro-responsive device and changed in accordance with the progress of the car along the track, and means actuated by said distance 80 mechanism effective to apply the brakes of the train after the train has traveled more than a certain distance since said electro-responsive device has changed from clear to caution or after it traverses a predetermined 85 distance since said electro-responsive device has changed to danger unless the engineer has evidenced his vigilance by actuating said acknowledging device in response to each of such adverse changes of said relay. 90

28. An automatic train control system of the continuous inductive type in which the vehicle is permitted to proceed if current flowing in the track rails is detected by suitable car-carried apparatus and in which certain short sections of the track cannot be supplied with such trackway current comprising, an electro-responsive device responsive to the flow of current in the track rails energized under clear traffic conditions ahead, permissive speed means, actual speed means, means for applying the brakes of the train if the actual speed exceeds the permissive speed, means abruptly reducing the permissive speed after a predetermined distance of 105 travel of the vehicle after de-energization of said electro-responsive device, a manually operable acknowledging device which if operated prior to the de-energization of said electro-responsive device prevents the abrupt 110 reduction in the permissive speed, whereby operation of said acknowledging device by the engineer prior to an adverse change in traffic conditions permits the train to proceed less restricted and whereby such acknowledgment is not necessary to avoid restriction in the speed at which the train may travel without having the brakes automatically applied by the passage of the train by a track section where there is no trackway 115 current flowing providing this section is shorter than said predetermined distance.

29. An automatic train control system of the continuous inductive type in which the train is permitted to proceed restricted only 120 to a maximum speed limit if current flowing in the track rails is detected by suitable car-carried apparatus in consequence of which means is necessary to permit the train to travel in territory not equipped for train 125 130

control purposes comprising, a control relay normally energized in response to currents flowing in the track rails adapted to assume a normal, a reverse and a de-energized position respectively, a non equipped territory relay having a pick-up and a stick circuit which if energized permits the train to proceed restricted only to a maximum speed limit, means for closing the pick-up circuit 10 for said non-equipped territory relay if said control relay is in its normal position, means for closing said stick circuit when said control relay is in its de-energized position, trackway means at the entrance to non- 15 equipped territory for causing said control relay to change from the normal to the de-energized position upon passage of the train into such non-equipped territory, and supplemental means for picking up said non- 20 equipped territory relays including a manually operable device and means effective if the speed is reduced to a predetermined extent to close said pick-up circuit if said manually operable device is operated at the 25 same time.

30. An automatic train control system of the continuous inductive type in which traffic conditions are continuously transmitted from the trackway to suitable vehicle carried influence receiving means in response to current flowing in the usual track circuit in accordance with the closed circuit principle so that such current is flowing under favorable traffic conditions comprising, a control relay energized in response to such track circuit current, automatic means for effecting an automatic brake application upon de-energization of said control relay, manually operable acknowledging means which if 35 manually operated just prior to the de-energization of said control relay by reason of the train entering a zone occupied by another train prevents a brake application by said automatic means so long as said control means remains de-energized but becomes ineffective if said relay is energized even if only momentarily, whereby manual operation of said acknowledging device is necessary upon entrance of the train into each of 40 a plurality of successive occupied zones because just before entering such occupied zone the section in which the train in ques-

tion is moving is not occupied by another train ahead.

31. An automatic train control system of 55 the continuous inductive type in which traffic conditions are continuously transmitted from the trackway to suitable vehicle carried influence receiving means in response to currents flowing in distinctive trackway circuits comprising a three-position control relay energized to assume a normal position in a clear zone assume a reverse position in a caution zone and assume a de-energized position in an occupied zone, automatic means 60 for effecting a brake application upon entrance of the train into an occupied zone, acknowledging means including a manually operable device which acknowledging means if effective prevents such automatic brake application and is effective if said manually operable device is operated upon entrance of the train into an occupied zone and remains effective to prevent such brake application 65 only so long as the train is traveling in an occupied zone, whereby manual operation of said manually operable device is necessary to avoid a brake application upon entrance of the train into each of a plurality of successive occupied zones, because each of said occupied zones changes to a non-occupied zone just before the train leaves such zone by reason of the necessary spacing between 70 trains to avoid a collision.

32. Car-carried apparatus for automatic 80 train control systems comprising, means automatically operated to indicate clear, caution or danger in accordance with traffic conditions ahead, penalizing means of the type which if momentarily changed will remain in the changed condition until restored to its previous condition, said penalizing means being biased to its effective condition but maintained in its normal inactive condition so long as and only when said first 85 mentioned means is in its clear or caution condition but not when it is in its danger condition, and manually operable means for independently maintaining said penalizing means inactive.

In testimony whereof we hereby affix our signatures.
